Application November 6, 1934, Serial No. 751,738

35 Claims.

(Cl. 51—52)

The present invention relates to machines for producing gears and particularly to machines for grinding longitudinally curved tooth gears, such as spiral bevel and hypoid gears. In a still more 5 particular aspect, the invention relates to longitudinally curved tooth gear grinding machines in which a rotary dished grinding wheel is employed and the wheel is swung to and fro along the length of a tooth to grind the side surface of the tooth 10 from end to end.

One object of the invention is to provide a spiral bevel and hypoid gear grinding machine of the dished wheel type that will be of improved design and simpler in construction than machines of 15 this type previously built.

A further object of the invention is to provide a grinding machine in which separate means are provided for controlling the preliminary or rough grinding and the final or finish grinding operations 20 and in which the means controlling the finish grinding operations is so constructed that a finer quality of finish will be obtained.

Still another object of the invention is to provide a grinding machine in which feed mechanism 25 is located directly behind the part being fed whereby to reduce the mass of the parts being moved and to obtain a direct and steadier feed.

Still another object of the invention is to improve the accuracy of grinding by providing a 30 gear grinding machine in which the dressing mechanism is mounted on a relatively fixed part of the machine and the wheel is moved up to the dressing mechanism for dressing, thereby insuring that the wheel is always dressed in the same position and to the correct pressure angles.

A further object of the invention is to provide an improved and simplified mechanism for dressing simultaneously the two sides and the tip of a 35 grinding wheel.

Still another object of the invention is to provide in a machine of the dished wheel type, means whereby the gearing for producing the swing of the wheel can also be actuated at will to swing the wheel beyond its normal working path 40 to bring it to dressing position.

A further object of the invention is to provide mechanism for quickly clamping the grinding wheel head at a plurality of points simultaneously or for releasing the same, and in this, as in 45 certain other aspects, the invention has utility in connection with gear cutting as well as gear grinding machinery and in connection with machine tools generally.

A further object of the invention is to provide 50 in a machine tool, a unitary control for the chucking mechanism, the mechanism for moving the workhead to and from operative position, and the mechanism for clamping the workhead in operative position. In this connection, a further 55 object of the invention is to provide means which

will safeguard the operator of the machine and insure that the work is chucked to his satisfaction before the workhead can be moved to operative position. Still further, means is provided that insures that the workhead is actually in 5 operative position before it is clamped.

Still another object of the invention is to provide a machine in which the grinding wheel is dressed automatically at the end of each grinding cycle as, for instance, at the ends of both the 10 rough and finishing grinding operations.

Still another object of the invention is to provide a machine in which the grinding wheel will be advanced automatically relative to the work after each dressing operation to compensate for 15 wheel-wear. In this connection, a further object of the invention is to provide means for automatically clamping and unclamping the grinding wheel head prior to and after, respectively, advancement of the wheel. 20

A still further object of the invention is to provide means operative at the end of rough-grinding for automatically shifting the means that controls the feed during rough-grinding out of operative position and bringing the means that 25 controls the feed during the finishing grinding into operative position.

A still further object of the invention is to provide a machine having means for automatically releasing the workhead and for moving the 30 workhead from operative position to chucking position when the operations on the work have been completed and for dechucking the completed work piece during the latter movement.

Further, it is an object of this invention to 35 combine the various automatic features described in a single machine so as to provide a gear grinding machine which will be fully automatic in operation and which will require no attention from the operator whatsoever from the time the 40 machine is started until the work on the gear has been completed and the gear dechucked.

The invention also includes various other improvements and refinements having to do with the production of machinery for producing gears, 45 all of which will appear clearly from the following description and from the appended claims when read in conjunction with the accompanying drawings.

Two different embodiments of the invention 50 have been illustrated in the drawings, one a machine which is semi-automatic in operation and the other a machine which is fully automatic.

In the drawings:
Fig. 1 is a side elevation, with parts broken 55 away, of a semi-automatic machine for grinding spiral bevel and hypoid gears;

Fig. 2 is a vertical sectional view on an enlarged scale taken longitudinally through the 60 grinding-wheel head;

Fig. 3 is an elevational view of the wheel head, looking at the grinding wheel and dressing mechanism;

Fig. 4 is a fragmentary vertical sectional view through the tool end of the machine and taken at right angles to the view of Fig. 2;

Fig. 5 is a fragmentary view showing details of the grinding wheel oscillating mechanism and parts of other drives of the machine, the view being a sectional view taken approximately on the line 5-5 of Fig. 4;

Fig. 6 is a plan view of the tool head, the view being on a somewhat reduced scale and parts being broken away;

Fig. 7 is a transverse vertical sectional view through the workhead of the machine on an enlarged scale;

Fig. 8 is a view of the workhead clamp taken at right angles to the view of this clamp seen in Fig. 7;

Fig. 9 is a rear end view of the workhead showing details of the index mechanism;

Fig. 10 is the section on the line 10-10 of Fig. 9;

Fig. 11 is a diagrammatic view showing the connection between the rotary control valve, the chucking mechanism, the mechanism for moving the workhead, and the mechanism for clamping the workhead, all of which mechanisms are controlled by said valve;

Fig. 12 is a side elevation of the stop-plate for controlling the movement of the control-valve;

Figs. 13 to 16 inclusive are diagrammatic views illustrating the operation of the control-valve;

Fig. 17 is a development of the rotary part of this valve;

Figs. 18 and 19 are developments of the feed-cams controlling the rough and finish grinding operations, respectively;

Fig. 20 is an enlarged plan view of the feed cam and follower;

Figs. 21 and 22 are views of the dressing mechanism, partly in section, and taken at right angles to one another; Fig. 22 showing, also, diagrammatically the connection between the dresser control valve and the dressing mechanism;

Figs. 23 and 24 are plan sectional views, showing two different positions of the dressing mechanism in the act of dressing a grinding wheel;

Fig. 25 is a section on the line 25-25 of Fig. 4;

Fig. 26 is a partial plan view corresponding to Fig. 6 but on a somewhat enlarged scale, showing the wheel-head of a modified form of machine constructed to be fully automatic in operation;

Fig. 27 is a sectional view of the control-valve used in the fully automatic machine for controlling the chucking operation, the movement of the workhead, and the clamping of the workhead, and showing the mechanism for operating this valve;

Fig. 28 is a side elevation of the stop-plate for controlling the movement of this valve;

Fig. 29 is a fragmentary sectional view of the line 29-29 of Fig. 26;

Fig. 30 is a fragmentary sectional view on the line 30-30 of Fig. 26;

Fig. 31 is a fragmentary sectional view on the line 31-31 of Fig. 26;

Fig. 32 is a section on the line 32-32 of Fig. 26;

Fig. 33 is a fragmentary sectional view, showing the two needle valves that control the rate of dressing of the grinding wheel prior to rough-grinding and prior to finish grinding, respectively;

Figs. 34 and 35 are views showing two different positions of the cycle-control-bar at two dif-

ferent stages in the operation of the fully automatic machine; and

Fig. 36 is a diagrammatic view of the electrical and hydraulic circuits of the fully automatic machine and illustrating the method of operation 5 of this machine.

The advantages of a rotating and swinging dished or cupped grinding wheel for grinding longitudinally curved tooth gears have already been clearly disclosed in the U. S. patent to Taylor, No. 1,830,971 of November 10, 1931. In the gear-grinding machines illustrated in the accompanying drawings, this type of grinding wheel is employed. The tooth grinding action is produced, as in the Taylor patent, by rotating the wheel 15 at high speed on its axis and simultaneously swinging the wheel about an axis passing through the center of longitudinal curvature of the side tooth surface or surfaces being ground. The present invention constitutes in several respects 20 an improvement over the Taylor patent as will now be described.

In the machines illustrated, the gear is held stationary during grinding and the grinding of the tooth surfaces for their full height is effected 25 by feeding the rotating and swinging grinding wheel into the gear until full depth position is reached. One side of a tooth space may be ground at a time, but preferably both sides of the tooth space will be ground simultaneously. When a tooth surface or a pair of tooth surfaces have been ground, the wheel is withdrawn and then the gear is indexed. The alternate feed and withdrawal continues until the gear is completed.

To secure the best possible results as regards 35 quality of finish of the tooth surfaces ground, we have provided separate feed cams for the rough and finish grinding operations. The two

cams are mounted upon the same shaft and this shaft is shiftable axially to bring the cams alternately into operative position. The roughing cam is so constructed as to provide a continuous feed during grinding and stock is removed throughout the whole of the feeding movement and as soon as the wheel reaches full depth position it is withdrawn. The finishing cam is constructed, however, to produce a dwell of the grinding wheel in full depth position at the end of the feed movement. This dwell insures cleaning up of the tooth surfaces and a smooth tooth-surface finish. The finishing cam, moreover, is designed to produce a finer feed than the roughing cam and in this way, also, conduces to a 50 better quality of tooth surface finish.

A further feature of the invention, which also 55 makes for improved quality, is the mounting of the cams themselves. The grinding wheel is journaled in an oscillating carrier which is oscillated to produce the longitudinal swinging motion of the wheel. This carrier is journaled in spaced 60 bearings in the wheel head and the feed-cam shaft is mounted in the head to extend between these bearings so that the feed-cams operate directly behind the wheel and substantially in line therewith. With this construction, the mass 65 being moved during feed is reduced and a steadier feed movement is obtained.

The wheel head is adjustable axially of the swinging carrier to compensate for wear of the wheel. One of the constructional features of 70 the present machine and one having general application is the mechanism for clamping the wheel head to the frame after adjustment. In the machines shown, the clamping mechanism includes four T-bolts that engage the frame at 75

four spaced points. Each of the T-bolts is secured to a piston that is movable in a cylinder bored in the wheel head and the four pistons are controlled from a single centrally located valve.

5 Thus the head can be clamped or released simultaneously at four different points by operation of this single control valve. This very much expedites handling of the machine.

The dressing mechanism itself is also novel. 10 Three diamonds are employed, two for dressing opposite sides of the wheel and the third for dressing the tip of the wheel. One of the side dressers is mounted upon the head of a hydraulically-actuated piston-rod. The end or tip 15 dresser is mounted upon a swinging arm and this arm carries a follower that engages a cam-projection on the head of the piston-rod so that as the first-mentioned side dresser moves back and forth under actuation of its piston, the tip dresser 20 is swung back and forth to dress the tip of the wheel. The other side dresser is also mounted upon a swinging arm and this latter swinging arm carries a follower that engages a cam-projection upon the first mentioned swinging arm, 25 the arrangement being such that as the tip dresser swings back and forth as already described, it will impart a swinging motion back and forth to the second side dresser to dress the side of the wheel. The three dressers are, therefore, actuated simultaneously from a single hydraulically operated piston.

The dressers are all mounted upon a drum and the arms which carry the two side dressers are each angularly adjustable upon this drum. The 30 angular adjustments of the side dressers permit setting them to dress the opposite sides of the grinding wheel to any desired pressure angles. The tip dresser is longitudinally adjustable on its arm so that the grinding wheel may be dressed 35 to any desired point-width. The drum itself is laterally adjustable on the wheel-head and this adjustment is in a direction radial of the axis of swing of the grinding wheel so that the diamonds can be adjusted to dress wheels of different diameters.

To dress the grinding wheel, it is swung up out of its normal operating path to bring it into operative relation with the dressing diamonds which are, as described, relatively fixed. The train of 40 gearing for oscillating the wheel carrier includes a differential and the housing of this differential is held stationary during grinding. To swing the grinding wheel to or from dressing position, a hydraulically-operated piston is actuated. This 45 piston is connected to a rack that is adapted to rotate the housing on actuation of the piston. Adjustment of the rack relative to the piston allows of positioning the grinding wheel to grind gears of different spiral angles, but the wheel is 50 always moved to the same position for dressing regardless of its spiral angle adjustment.

The indexing mechanism of the machine illustrated is of the notched plate type and is actuated from a cam that is driven in timed relation 55 with the feed cam shaft.

In order to place a gear on the machine or remove a gear after it has been ground, the workhead is moved to loading position. The movement of the workhead to and from loading position, 60 the clamping of the workhead in operative position, and the chucking and dechucking of gears upon the work spindle are controlled from a single rotary valve. This valve controls a piston that moves the workhead to and from loading 65 position, a piston that actuates or releases the

workhead clamp, and a piston that controls the operation of the chucking mechanism.

On both the semi-automatic and the fully automatic machines, the rotary valve just described is manually operable in one direction to first 5 chuck a gear on the work spindle, then move the workhead into operative position, and then clamp the workhead in operative position. A stop or cam-plate is provided in conjunction with the valve just described to insure that the operator 10 will take a positive action between chucking and movement of the workhead to operative position and between movement of the workhead to operative position and clamping of the workhead. This insures that the operator will have the gear 15 properly lined up with the grinding wheel before he moves the workhead into operative position and it also insures that the workhead will have fully reached operative position before it is clamped.

In the return movement of the control valve, the workhead is released, then moved to loading position and the completed gear is dechucked. The steps take place automatically in the fully 20 automatic machine, after the gear is completely 25 ground.

In the machines illustrated, the work spindle is journaled in a slide that is vertically adjustable upon the workhead or column and the workhead or column slides on a base that is angularly adjustable upon a plate. The plate is in turn laterally adjustable upon the frame of the machine. The vertical and lateral adjustments permit of adjusting the gear relative to the grinding wheel for spiral angle. The angular adjustment is for the purpose of adjusting the gear in 30 accordance with its pitch cone angle.

In the semi-automatic machine, a shift from the roughing to the finishing feed cams and vice versa is effected manually by reciprocation of a 40 sleeve in which the cam shaft is journaled and a wedge is provided for holding this sleeve against movement when the finishing cam is in operative position so as to eliminate all possibility of vibration during the finish grinding operation. The 45 movement of the grinding wheel to and from dressing position is also effected manually as are, also, the advance of the grinding wheel head after dressing to compensate for wear and the operation of the valve that controls the T-bolts 50 for clamping this head. The rotary valve that controls chucking movement of the workhead to and from loading position and clamping or releasing of the workhead, in the semi-automatic machine is manually operable in both directions. 55 In this machine, the dressers are also manually controlled, a manually operable valve being provided for controlling the movement of the piston that actuates the dressers.

In the fully automatic machine the various operations described are automatic. This machine stops with the workhead at loading position, the work dechucked and the grinding wheel swung up to dressing position. When the machine is started, the grinding wheel is automatically 60 swung down into grinding position. This closes a contact that starts the main drive motor. The operator then manually rotates the control valve to chuck a gear, move the workhead into operative position and clamp the head in this position. 65 The machine then goes through the rough grinding cycle, the grinding wheel being fed into the gear to grind a tooth space of the gear and being then withdrawn and the gear being then indexed and so on until all of the tooth surfaces 70 75

of the gear have been ground. The automatic stop mechanism of the machine then operates to stop the main drive motor and cause the grinding wheel to be again swung up to dressing position. When the grinding wheel reaches dressing position, a contact is made that shifts the roughing cam out of operative position and brings the finishing feed cam into operative position. The wheel head is then automatically unclamped and fed forward a distance equal to the amount of stock to be removed from the grinding wheel in the dressing operation. At the end of this advancing movement of the wheel head, a valve is shifted that controls the dressing mechanism and the dressing mechanism goes through its cycle to dress the grinding wheel. At the completion of the dressing operation, the grinding wheel is automatically returned to grinding position and the machine then goes through its finish grinding cycle. The wheel is alternately fed into the gear to finish grind each tooth space, and withdrawn and during the periods of withdrawal, the gear indexed. When all of the teeth have been finish ground, the automatic stop mechanism again trips to swing the grinding wheel up to dressing position and the shaft carrying the feed cams is again shifted axially. The grinding wheel head is unclamped and advanced and the wheel is dressed, as before. The shift of the feed cam shaft at this time, however, will break the starting circuit to the machine so that the completion of the dressing operation will not cause the wheel to be again swung down into operative position. This shifting movement of the cam shaft will also release the rotary control valve. This valve will then be rotated automatically under actuation of a spring to automatically release the workhead, move it to loading position and dechuck the gear. Thus the whole operation of the machine takes place automatically, without requiring any attendance of an operator, from the time that the machine is started and the gear is chucked until the gear is completed both rough and finish ground, moved to loading position and dechucked.

The principal features of the invention and the method of operation of the machines shown in the accompanying drawings have been described in general terms. Reference will now be had to the drawings for a more detailed description of the invention and of these machines. The semi-automatic machine will be described first.

30 designates the base or frame of this machine and 31 (Figs. 1 and 2) designates a housing or upright which is rigidly secured to this frame at one end thereof and which may be integral therewith. This housing or upright 31 is hollow and is formed with plane top surfaces on which there slides a wheel-head 32.

Mounting for the grinding wheel

Mounted in the wheel-head 32 is an oscillatable and slidable wheel-carrier or quill 34. This wheel-carrier or quill 34 is of irregular shape as will be clear from Fig. 2 of the drawings.

The column or upright 31 is formed at its forward end with a cylindrical bearing 35 (Figs. 2 and 3). There is a cylindrical plate or guide 36 secured to the quill 34 at the front end thereof by screws 37. This plate 36 has its bearing in the bearing 35 of the column 31 and forms a guide for the quill 34 in its oscillatory and sliding movements.

75 There is a sleeve 38 secured in an opening in

the rear end of the quill 34 by screws 39. This sleeve is mounted for rotating and sliding movements in a bearing formed in an arm 40 that is integral with the plate or wheel-head 32 and depends therefrom.

5 There is a ball-thrust bearing 42 mounted in the quill 34 directly behind the cylindrical drive-plate 36. There is a sleeve 43 mounted in this bearing and formed at its rear end with a flange 44 that seats against the rear face of the bearing. 10 A cam-follower or projection 45 (Figs. 2 and 20) is secured to this flange by screws 46.

Pending from the plate or wheel-head 32, adjacent its forward end is a hollow bearing or arm 50 (Figs. 2 and 4). This arm 50 is formed at 15 its lower end with a semi-cylindrical seat or bearing 49 (Fig. 4). This bearing 49 aligns with the bore of the sleeve 43 already referred to. Mounted in the bearing 49 and the sleeve 43 is a sleeve 51. This sleeve 51 is held in the bearing 49 20 by a cap-member 54 and is secured against axial movement relative to the arm 50 by a pin 52 and a screw 53 that are mounted in a cap-member 54 and engaged in the sleeve. The cap-member 54 is secured to the depending bearing 50 by 25 bolts 55. The sleeve 51 carries a key 56 that engages in an elongated key-way 57 that is formed internally in the sleeve 43. Thus the sleeve 43 is held against rotation relative to the sleeve 51 while relative sliding movement between the two 30 sleeves is permitted.

60 designates a plate which is secured to the quill 34. This plate has a forwardly projecting stem or stud 61 that is journaled on bearings 62 in the sleeve 51. The forward end of this stud 35 61 is of reduced diameter and is mounted in a thrust-bearing 63 that is slidably mounted in the sleeve 51. A nipple 64 is threaded in the forward end of the sleeve 51 and between this nipple and the bearing 63 there is interposed a coil 40 spring 65.

Journaled in the quill 34 is a wheel-spindle 70 which is tapered at its forward end to receive the adaptor 71. The cupped grinding-wheel W used on the machine is secured to the adaptor by nuts 45 72 and the adaptor is secured to the spindle 70 by threading up on the nut 73 which threads on the end of the wheel-spindle. The wheel-spindle 70 is journaled on anti-friction bearings 74 and 75 in a sleeve 76 that is secured to the 50 quill 34 by bolts 78. The usual labyrinth-seal 77 is provided at the forward end of the spindle to prevent entry of dirt or grit into the bearings.

Drive to the grinding wheel

55 The grinding-wheel spindle 70 is driven from a motor (not shown) that is mounted in the base or frame of the machine. The drive is from the motor through a belt 80 to a pulley 81 that is keyed to a hollow-shaft 82 which is journaled 60 on anti-friction bearings 83 and 84 in an end-plate 85 which is secured by screws 86 to the upright or housing 31. The belt 80 and pulley 81 are protected by a guard 87 which is secured to the housing 31 in any suitable manner.

65 Journaled on anti-friction bearings 90 and 91 in the sleeve 38 is a shaft 92 which has a telescoping splined connection with the hollow shaft 82. Keyed to the shaft 92 is a bevel gear 93 that meshes with a bevel gear 94. The gear 94 is 70 keyed to a shaft 95 which is journaled on anti-friction bearings 96 and 97 in a sleeve 98 that is fixedly secured in the quill 34.

75 Keyed to the shaft 95 at its forward end is a pulley 100. This pulley drives a pulley 101

through a belt 102. The pulley 101 is keyed to the rear end of the wheel-spindle 70.

Through the gearing just described, a rotary motion is imparted to the grinding-wheel to produce the grinding action. We shall now describe the mechanism for producing the swinging motion of the grinding wheel required to move the wheel longitudinally along the tooth surfaces to be ground to grind the tooth surfaces from end to end.

Wheel oscillating mechanism

Mounted in the base or frame of the machine is a motor 105, (Fig. 1). This drives a vertical shaft 106 through a suitable coupling 107. The shaft 106 carries at its upper end a bevel pinion 108 that meshes with a bevel gear 109 secured to a shaft 110. The shaft 110 has a spur gear 112 fastened to it at its outer end. This spur gear 20 meshes with a spur gear 113 (Figs. 1 and 5) which is splined to a shaft 114. The shaft 114 is journaled on anti-friction bearings 115 in the column 31 and a bevel pinion 116 is keyed to the shaft at its inner end. This pinion meshes with a bevel gear 117 which is secured by screws 118 to a crank-plate 120. The crank-plate is integral with a shaft 121 that is journaled on anti-friction bearings 122 and 123 in the column 31. The crank-plate is of the usual construction and is formed with a crank-plate slot 124 (Figs. 4 and 5) which receives the adjustable block 125 that carries the crank-pin 126. The crank-pin 126 is connected by a rod 127 to a pin 128 which is secured by a nut 129 in a link 130. The rod 127 is secured to the crank-pin 126 by a nut 131.

The link 130 is connected to a shaft 132 and is held thereon by the nut 133. This shaft is journaled on anti-friction bearings 135 and 136 in the sleeve 137 of a differential-housing 138.

The shaft 132 is integral with one of the side gears 140 of the differential. This gear 140 meshes with the planetary-gears 141 and 142 which are journaled on anti-friction bearings 143 and 144, respectively, in the differential housing, and are also mounted upon the differential-spider 145. The planetary-gears 141 and 142 mesh with a differential side gear 146. This gear 146 is integral with a shaft 147 that is journaled on anti-friction bearings 148 and 149 in a sleeve 150 that is integral with the differential housing. The sleeves 136 and 150 of the differential housing are journaled in bearings 151 and 152, respectively, that are formed integral with the column or housing 31.

There is a spur gear 155 keyed to the shaft 147 at its rear end and this spur gear meshes with a spur gear segment 156 (Figs. 4 and 2) that is integral with the quill 34.

Through the gearing just described, then, an oscillating motion is imparted to the quill and through the quill to the grinding wheel to swing the grinding wheel back and forth along the length of the gear teeth being ground. We shall next describe the mechanism for imparting to the grinding wheel its alternate movements of feed and withdrawal.

Wheel feed mechanism

Mounted on the shaft 114 already referred to (Figs. 1 and 5) and splined thereto is a spur gear 160 that meshes with a spur gear 161 which is keyed to a stub-shaft 162. This shaft is journaled on anti-friction bearings 163 and 164 in a quadrant 165 that is secured to the housing or upright 31 by a bolt 166.

The spur gear 161 meshes not only with the spur pinion 160 but also with a spur gear 168 (Fig. 1) which is secured to a shaft 169 that is journaled in the column 31 and which has fastened thereto a bevel gear 170. This bevel gear 5 meshes with a bevel gear 172 (Figs. 1 and 5) that is keyed to a shaft 173. This shaft 173 is journaled on anti-friction bearings 174 and 175 in the column 31. At its forward end, the shaft 173 has a sliding splined engagement with a sleeve 10 10 177 that is journaled on anti-friction bearings 178 and 179 in the column 31. A bevel gear 180 is keyed to the sleeve 177 and meshes with a bevel gear 181 that is keyed to a vertical shaft 182 that is suitably journaled in the column 31. 15

This vertical shaft 182 has secured to its upper end a bevel gear 184 (Fig. 6) which meshes with a bevel gear 185 that is secured to a horizontal shaft 186. The shaft 186 carries at its inner end a bevel pinion 187 which meshes with a bevel gear 188 (Figs. 6 and 2). The bevel gear 188 is keyed to a sleeve 189 that is journaled on anti-friction bearings 191 and 192 in a bracket 193. This bracket is suitably secured to the upper face of the wheel-head 32 and the horizontal shaft 186 25 is journaled in this bracket.

The sleeve 189 has splined engagement with a vertical cam-shaft 195 that is journaled on anti-friction bearings 196 and 197 (Fig. 2) in a sleeve 198 which is vertically reciprocable in the 30 cylindrical bore of the depending arm 50 already referred to.

There is a cam-member 200 fixedly secured to the lower end of the shaft 195. This cam-member is provided with two peripheral cam-tracks 35 201 and 202 (see Figs. 18 and 19). One of these tracks is a roughing-cam track and the other a finishing-cam track. They are adapted to be engaged selectively with the projection or follower 45 to impart feed movement to the quill 34 40 and the grinding wheel.

To bring either cam-track into engagement with the follower 45, the sleeve 198 is moved vertically. To this end a handle or crank 205 (Fig. 1) is provided. This is secured to a shaft 206 45 that is journaled in the plate or head 32 and that carries at its inner end a spur pinion 207 (Fig. 2). This pinion meshes with a rack 208 cut into the peripheral surface of the sleeve 198 adjacent to the upper end thereof. 50

The sleeve 198 is provided adjacent to its lower end and at a point diametrically opposite the rack 208, with a slot 210 that extends from its lower end upwardly and tapers outwardly. This slot receives a tapered key 211 which is adjustably secured in the arm 50 by means of bolts 212. These bolts pass through an elongated slot 213 in the arm 50 and thread into the key 211. The key 211 operates to hold the sleeve 198 against rotation and, in the lower position of the sleeve, 60 when the finishing cam 210 is engaged with the follower 45, acts as a wedge to hold the sleeve rigidly against vibration, thereby to insure a perfect finish in the finish-grinding operation.

A lay-out of the track of the roughing cam is 65 shown in Fig. 18. In the rotation of this cam, the quill 34 is first fed at a rapid rate toward the work, but when the grinding wheel reaches the position where it contacts with the gear, the rate of feed is reduced and the wheel is fed on into 70 full depth engagement with the gear at a much slower rate. The slow-feed prevents an excessive burden from being placed on the wheel and produces a rough-finish on the sides of the teeth at the end of the rough-grinding operation that will 75

lend itself well to the ensuing finish-grinding operation. When the wheel reaches full-depth position, it is withdrawn and when the wheel is clear of the gear, the gear is indexed. To insure that the indexing will be completed before the wheel is again fed back toward the work, a dwell in the cam-track is provided, as indicated.

The track of the finishing cam differs somewhat from that of the roughing cam as will be seen from Fig. 19. When the finishing cam is in use, the quill 34 is fed at a rapid rate toward the work until the wheel contacts the gear. Then the feed is reduced. The slow-feed produced by the finishing cam is, however, somewhat more rapid than the slow-feed of the roughing cam for with the finishing cam, the grinding wheel reaches full depth position sooner than with the roughing cam. There is a dwell provided on the finishing cam, though, that maintains the grinding wheel in full depth engagement with the gear for an appreciable time, instead of causing it to be withdrawn immediately after it reaches full depth position as is the case with the roughing cam. This dwell in full depth position allows the wheel to clean up the sides of the tooth space, producing a smoother tooth surface finish and insuring more accurate tooth-spacing. At the end of the dwell, the wheel is withdrawn and the gear is indexed as before.

To insure accurate dressing of the grinding wheel, it is desirable to dress it always in the same position. The wheel is always swung up to the same position for dressing as will hereinafter be described. It is preferred to dress it always in the same relative depthwise position also. To this end it is preferably dressed in the full withdrawn position. The dwells in the cam-tracks which serve for indexing therefore preferably determine the positions at which the wheel is dressed, as indicated in Figs. 18 and 19.

Work-head adjustments

The gear G to be ground is secured to the work spindle 220 of the machine (Figs. 1 and 7). The work spindle is suitably journaled in a carrier 221, being secured therein by a cap-member 222 which is secured to the carrier 221 by bolts 223. The carrier is adjustable vertically on the ways of a column or head 225, the adjustment being effected by rotation of the screw-shaft 226. This shaft is rotatably mounted in the column 225 and threads into a nut 227 that is secured to the carrier 221. There is an index-pointer 228 secured to the carrier 221. This pointer reads against graduations provided on the column so as to permit the vertical adjustment of the carrier on the column to be made accurately. The screw-shaft 226 is provided with a micrometer-dial 229 for fine adjustments.

To secure the carrier 221 rigidly in any position of its vertical adjustment, a brace 230 is provided. This brace is fixedly secured at its lower end to the column 225 by a bolt 231, and it is adjustably secured to the carrier 221 by the bolt 232 which passes through an elongated slot 233 in the brace and which threads into the carrier.

The head or column 225 is mounted for longitudinal movement and adjustment on a base 235, the base being formed with ways 236 and 237 on which the head or column slides. The movement of the head 225 is for the purpose of bringing the gear to operative position for grinding or withdrawing the head to loading position where a completed gear can be dechucked and a new gear placed upon the machine.

The described movement of the workhead or column 225 is effected by reciprocation of a piston 240 (Fig. 11). This piston reciprocates in a cylinder 241 (Figs. 7 and 11) which is suitably secured to the base 235 at one side thereof. The piston 240 is secured by a nut 242 against the shoulder on a piston-rod 243 so that the piston is held against longitudinal movement relative to the rod. The piston-rod extends through the rear end cap and packing box 245 of the cylinder 241 and is threaded beyond the point where it passes through this packing box. This threaded portion of the piston rod engages a split-nut 247 which is secured in any suitable manner to the head or column 225.

The head 225 can be adjusted relative to the base 235 to adjust the gear in accordance with its cone distance by loosening the split-nut 247 and rotating the piston-rod 243. By application of fluid-pressure to opposite sides of the piston 240, the head can be moved from loading position to operative position or vice versa, depending upon the direction of application of the fluid-pressure.

The head 225 is secured in operative position by a clamping mechanism which will now be described. This clamping mechanism comprises a two-jaw clamp, the lower jaw of which is designated at 250 and the upper jaw at 251 (Figs. 7 and 8). The under jaw 250 engages under the ways 236 and 237 of the base 235, being formed with two contact-pads 252 at each end which contact with and engage under the ways. The lower jaw is also provided with wings 253 at either side intermediate its ends. These wings have opposed inwardly extending projections 254. These projections have hardened contact-tips 255 secured in their under faces.

The upper jaw has a hardened contact tip 256 secured in its under face at one end of the jaw. This contact tip 256 is adapted to engage a hardened contact tip 257 which is secured in a projection formed on the head or column 225. The upper jaw has side projections or lugs 258 which carry hardened contact tips 259 on their upper faces. These contact tips 259 engage the contact tips 255 carried by the lower jaw 250.

There is a piston rod 260 pivotally connected to the upper jaw 251 by a pin 261. The piston rod is connected to the jaw 251 at the end of the jaw opposite that which carries the contact tip 256. The piston rod 260 is secured to a piston 262 that reciprocates in a cylinder 264 which is integral with the workhead 225. The piston rod extends through the lower end cap and packing-box 265 of this cylinder and is guided in its movement by a guide-bracket 266 which is secured to the head 225 by screws 267.

The contact tips 255 and 259 have rounded contacting faces and they serve as fulcrums for the jaw 251 so that as the piston 262 moves up or down in the cylinder 264, the upper jaw 251 is rocked about these contact tips to engage or release the clamp, depending upon the direction of movement of the piston.

The base 235 is angularly adjustable upon a plate 270 (Figs. 7 and 11), the base 235 being formed with a hub 272 at its front end that swings on a pin 273 which is secured in the plate 270. The base 235 adjusts about this pin 273 as a center. The base 235 is secured in any adjusted position by T-bolts 274 which engage in arcuate

slots 275 that are formed in the plate 270 concentric to the pin 273.

The plate 270 is laterally adjustable on ways 271 formed on the base or frame 30 of the machine. The plate is secured on the frame 30 in any position of its lateral adjustment by T-bolts 278 which engage in T-slots 279 cut into the frame.

The vertical adjustment of the carrier 221 on the column 225 in combination with the lateral adjustment of the plate 270 on the frame enables the gear to be adjusted to grind the correct spiral angle on its teeth. The longitudinal adjustment of the head 225 on the base 235 is for the purpose of positioning the gear at the correct cone-distance, while the angular adjustment of the base 235 on the plate 270 is for the purpose of positioning the gear to the correct pitch cone angle.

Index mechanism

The index mechanism of the machine is of the notched-plate type and is similar in construction and in principle of operation to the index mechanism of the Bullock et al. Patent, No. 1,786,697 of Dec. 30, 1930 and will be described here very briefly, as reference may be had to that patent for a detailed description of the same.

280 (Fig. 9) designates the index plate. This is provided with a number of notches 281 equal to the number of teeth in the gear to be ground. It is secured in any suitable manner to the work spindle of the machine. The index plate and with it the work spindle are held against rotation during grinding of a tooth by a locking-dog 282 which is secured to a lever 283 which is pivoted about a pin 284. This pin 284 is mounted in the index-guard 285 which is fixed relative to the work spindle carrier 221. The index lock-dog 282 is normally held in locking position by a coil-spring 289 which is mounted upon a pin 286 that is slidable in a lug 287 formed on the guard 285 and that is pivotally connected to the lever 283 by means of the pin 288.

45 Rotatably mounted upon the work spindle is an arm 290. Pivottally mounted upon this arm at 291 is a pawl 292. This pawl has a projection 293 which is adapted to engage in a notch of the index-plate 280 to rotate the index plate, when the lock-dog 282 is disengaged therefrom. The pawl is constantly urged toward engaging position by means of a spring-pressed plunger 294 which is housed in the arm 290. It is held out of engagement with the index plate, as long as the lock-dog is engaged with the plate, by engagement of the cam-surface 296 of the lever 283 with a roller 297 carried by the pawl.

60 The arm 290 carries a trip-dog 298. This trip dog is pivotally mounted on the arm 290 by a pin 299. It is constantly urged in one direction about its pivot by means of a spring-pressed plunger 300 which is housed in the arm 290. An adjustable limit-stop 301 which threads into the arm 290, limits the movement of the trip-dog in the other direction. The trip-dog 298 is adapted to engage a pin 302 that is secured in the lever-arm 283.

65 As the arm 290 rotates in a counter-clockwise direction looking at Fig. 9, the trip dog engages the pin 302, lifting the arm 283 and disengaging the lock-dog 282 from the index plate. The spring-plunger 294 then forces the pawl 292 into engagement with the index plate and the continued rotation of the arm 290 in the counter-clockwise direction rotates the index plate, in-

dexing the work-spindle. During this movement, the trip-dog 298 rides under the pin 302 and the lock-dog 282 drops back onto the periphery of the index-plate. When the lock-dog reaches the next notch in the index-plate, it again locks up the 5 index-plate and the cam 296 acting on the roller 297 disengages the pawl 292. Movement of the arm 290 in the reverse or clockwise direction, re-sets the index mechanism.

The index mechanism is operated from a cam 10 310 (Figs. 1 and 5). This cam is keyed to a shaft 311 that is journaled on anti-friction bearings 312 and 313 in the column or upright 31 in axial alignment with the shaft 121. The cam 310 is driven from the shaft 173 through a spur-pinion 315 which is keyed to the shaft 173 and which meshes with a spur-gear 316 that is integral with the cam 310.

The cam rocks a lever 318 for actuating the index mechanism (Fig. 1). This lever is pivoted 20 at 319 on the column 31. At one end it carries a roller 320 that engages in the track 322 of the cam 310. At its other end, the lever 318 has an adjustable pivotal connection with a bar 323, the connection being through a bolt 324 25 that engages in an arcuate slot 325 formed in the lever arm. The bar 323 is pivotally connected at 327 with a second bar 328. This second bar 328 slides in a guide-bracket 329 which is secured in any suitable manner to a side of the 30 frame or bed of the machine. The bar 328 is further guided in a second bracket 330 which is secured by bolts 331 to the bed or frame of the machine (Figs. 1 and 9).

The bar 328 is formed on its under face with 35 rack-teeth 332 which mesh with a spur-pinion 333. The pinion 333 is integral with a stub-shaft 334 that is journaled in the bracket 330. The shaft 334 is connected by a universal-joint 335 with a shaft 336 that has a sliding key-connection with a spur pinion 338 (Figs. 9 and 10). The pinion 338 meshes with a rack 340 cut into a cylindrical bar 341. This bar reciprocates in a bracket 342 carried by a bracket 343 (Fig. 1) that is secured by bolts 344 to one side of the 45 workhead or column 225.

The bar 341 is formed with a second rack 346 on the side opposite the rack 340. This second rack meshes with a spur pinion 347 that is keyed to a shaft 348. This shaft is journaled in the 50 bracket 342 and it has keyed to it a bevel gear 350 which meshes with a bevel gear 351 that is keyed to a vertical shaft 352. The bevel gear 351 is adjustable axially on the shaft 352 to bring it into proper meshing relation with the 55 gear 350. This adjustment is effected by the nut 353 which threads on the gear 351 and adjusts against the upper end of the bracket 342. The lock-nut 354 serves to lock the gear 351 against axial movement relative to the shaft 60 after adjustment.

Secured to the upper end of the shaft 352 is a spur-pinion 356 which meshes with a rack 357 cut on the side of a bar 358 that reciprocates in a guide-way formed in the index-guard 285. This bar 358 is formed on its upper side with rack-teeth 359 which mesh with a segment 360 secured to the rotating arm 290.

The cam 310 (Fig. 5) is driven from the shaft 70 173 in time with the feed-cams 201 and 202. Thus, through the train of gearing just described, the index mechanism is actuated in time with the feed mechanism of the machine so that during feed of the grinding wheel into the work, the

work spindle is stationary and when the grinding wheel is withdrawn, the work spindle is indexed.

Chuck mechanism

- 5 Any suitable type of chucking mechanism may be employed for securing the gear to be ground to the work spindle. A present preferred type of chucking mechanism is illustrated in the drawings. This comprises a draw-bar 365 (Figs. 1 and 11) which has an enlarged head at its front end, that engages the gear clamping plate 369, and which is urged to chucking position by a coil-spring 366. This spring surrounds the draw-bar and is interposed between a shoulder (not shown) in the bore of the work-spindle and a washer 367 that is carried by the draw-bar. The washer is held in position by a nut 368 that is threaded on the draw-bar and the tension of the spring 366 can be adjusted by threading upon this nut. The draw-bar 365 has contact at its rear end with a hardened rod 370 which slides in a bearing-member 371 that is secured in the end of the bore of the work-spindle by screws 372.
- 25 The rod 370 is held by the spring 366 in contact with the hardened tip 374 of a lever-arm 375. This lever-arm is pivotally mounted at 376 upon a guard-plate 377 that is pivotally mounted at 378 upon the index-guard 285 and that serves with the index-guard 285 to enclose the index mechanism.

The lever-arm 375 may be swung about its pivot-pin 376 to release the chuck against the resistance of the spring 366 by operation of the piston 380. This piston reciprocates in a cylinder 381 which is formed in the guard 285. The piston-rod 382 which is secured to the piston 380 by the nut 383 extends through the end-cap 384 of the cylinder 381 and engages the free end of the lever-arm 375. When fluid-pressure is applied to the front end of the piston 380, the chucking mechanism is released against the action of the spring 366, but when the motive-fluid is exhausted from the front end of the piston, the spring 366 operates to return the draw-bar to chucking position. The end-cap 384 is secured to the cylinder 381 by screws 385 (Fig. 9).

50 As a safety measure to prevent breakage of a grinding-wheel or damage to a gear caused by bringing the gear into engagement with the wheel with the gear loose on the work spindle, a safety limit-switch is incorporated in the circuit to the motor which operates the grinding wheel. This limit-switch is indicated at 387 in Figs. 9 and 11. The arm 388 of this switch carries a roller 389 which is in position to contact the end of the lever-arm 375. When the lever-arm 375 is moved to dechucking position, the switch opens to stop the grinding wheel drive motor and it is not until the blank is chucked that the lever-arm can close the switch to restart the motor.

65 Rotary valve for controlling chucking, workhead movement and clamping of workhead

As already mentioned, the chucking and release of the work, the movement of the workhead from loading position to operative position and vice versa, and the clamping of the workhead in operative position and release of same are all controlled from a single rotary valve. This valve has been designated at 390, see Fig. 11. This valve rotates in a sleeve 392 which is secured in

the bore of a valve housing 393. This valve housing is in the form of a cylinder which is secured by screws 394 to brackets 395 and 396 which are shaped to form end-caps for the cylinder. The brackets 395 and 396 are secured by 5 screws 397 and 398, respectively, to the plate 270 (see Fig. 1). The valve proper is recessed at various points around its periphery to provide a series of grooves as clearly shown in Fig. 17 which is a development of the valve. There are 10 six of these grooves arranged in three pairs or sets of diametrically opposed grooves or recesses. The two grooves of each set are designated by the same reference numeral, one set of grooves being designated at 400, another set at 401 and 15 the third set at 402.

The sleeve 392 is provided with a plurality of peripheral grooves, designated at 403, 404, 405, 406, 407, 408, 409 and 410, respectively, in Figs. 13, 14, 15, and 16. Radial ducts 413 communicate with the grooves 403 and radial ducts 414, 415, 416, 417, 418, 419, and 420 communicate with the peripheral grooves 404, 405, 406, 407, 408, 409 and 410, respectively. The several radial ducts extend inwardly from the respective 25 grooves to connect the grooves in the sleeve with the different grooves in the valve 390 as the valve rotates in the sleeve.

Oil is preferably used as the motive-fluid and is supplied under pressure to the valve from a 30 pump (not shown) driven by the motor 425 (Fig. 1). The supply-line 426 (Fig. 11) leads to the groove 406 in the valve-sleeve 392 and the pressure-fluid may be exhausted from the valve-chamber either through the duct 427 which communicates with the groove 403 in the valve-sleeve, or through the duct 428 which communicates with the groove 410 in the valve-sleeve. The two ducts 427 and 428 connect with a duct 429 which leads back to a sump provided in the frame or 40 bed of the machine.

The valve 390 is connected with opposite ends of the piston 262, which operates the workhead clamping mechanism, by ducts 430 and 431. The former communicates with the groove 405 in the 45 valve-sleeve 392 and the latter with the groove 407 in this sleeve. The valve 390 is connected to the front end of the piston 380, which operates the chucking mechanism, by a duct 432 which communicates with the groove 408 in the valve 50 sleeve 392. The valve 390 is connected with opposite ends of the piston 240, which moves the workhead from loading to operating position and vice versa, by a pair of ducts 434 and 435. The former communicates with the peripheral groove 55 404 in the sleeve 392 and the latter communicates with the peripheral groove 409 in the sleeve 392.

Figs. 13 to 16 inclusive illustrate the operation of the valve 390, these figures showing in dotted lines the grooves of the valve proper superimposed upon the ducts of the valve sleeve and showing the successive positions taken by the grooves in the rotation of the valve. Fig. 13 illustrates diagrammatically the position of the valve when the workhead is at the loading position. 65 Here the grooves 401 of the valve are in registry with the ports 416, 417, 418 and 419 in the valve sleeve and the grooves 400 are in registry with the ports 413, 414 and 415. Thus the lines 431, 432 and 435 (Fig. 11) are on supply from the line 70 426, while the lines 434 and 430 are on exhaust through line 427. In this position of the valve the piston 240 would be at the right of its cylinder instead of at the left as shown in Fig. 11, the piston 380 will also be at the right of its cylinder 75

der and the piston 262 would be at the lower end of its cylinder.

As the valve 390 is rotated, the grooves 401 rotate away from the ports 418, shutting off supply to the chuck-operating piston 380, and the grooves 402 are brought into registry with the ports 418 and 420. This allows the motive-fluid to be exhausted from the left-hand end of the cylinder 381 as viewed in Fig. 11. The gear is, therefore, chucked under actuation of the spring 366. At this point in the rotation of the valve 390, however, the workhead still remains at loading position and unclamped. This is because the line 435 still remains on supply through the ports 419, the grooves 401 and the ports 416, and the line 434 remains on exhaust through the ports 414, the grooves 400 and the ports 413, while the line 431 remains on supply through the ports 417, the grooves 401 and ports 416, and the line 430 remains on exhaust through the ports 415, grooves 400 and ports 413. The position of the valve 390 at this point in its rotation is illustrated diagrammatically in Fig. 14.

As the valve 390 is rotated further, the grooves 402 are brought into registry with the ports 419 and the grooves 401 are brought into registry with the ports 414. This places the right-hand end of the cylinder 241 (Fig. 11) on supply and the left-hand end on exhaust. Thus the piston 240 is moved to the left in this cylinder to the position shown in Fig. 11 moving the workhead from loading into operating position. The head is not clamped, however, at this point in the rotation of the valve 390 because the line 430 is still on exhaust through the ports 415, grooves 400 and ports 413 and the line 431 is still on supply through the ports 417, grooves 401, and ports 416. The position of the valve 390 at this point in its rotation is diagrammatically illustrated in Fig. 15.

The final step in the rotation of the valve 390 brings it to the position illustrated diagrammatically in Fig. 16. The grooves 401 are now brought into registry with the ports 415, while still remaining in registry with the ports 414. The grooves 402 are also brought into registry with the ports 417, while remaining in registry with the ports 418, 419 and 420. When the grooves 401 register with the ports 415, the line 430 is put on supply and when the grooves 402 move into registry with the ports 417 the line 431 is put on exhaust. This moves the piston 262 upwardly in its cylinder to rock the upper clamping-jaw 251 about its fulcrum and clamp the workhead in operating position.

As the valve 390 is rotated in one direction, then, it will be seen that the gear is first chucked, then the workhead is moved into operating position, and then the workhead is clamped. These operations take place in the reverse order when the valve is rotated back in the opposite direction.

To insure that the workhead is not moved into operating position until the gear has been clamped on the work spindle and to insure that the workhead is not clamped until it is fully in operating position, a special form of operating handle and detent has been provided. The handle comprises a body-portion 440 (Fig. 11) which is keyed to the projecting stem 441 of the valve 390. This stem is of reduced diameter and projects through an opening in the end-cap 396. The body-portion 440 of the handle is bored to receive a sleeve 442 which has a pressed fit therein. There is a rod 444 slidably mounted in the sleeve 442 which carries a pin or detent 445. A

coil-spring 446 is interposed between a shoulder or head formed on the rod 444 and the upper end of the sleeve 442. The rod 444 extends through an opening in the upper end of the sleeve 442 and is secured in a knurled-knob or grip 448 that is hollowed out to receive the sleeve 442.

There is a plate 450 (Figs. 11 and 12) secured to the bracket 396. This plate is formed on one side face with a cam groove 451 with which the detent 445 cooperates and in which it travels.

The operator moves the valve-handle in a counter-clockwise direction in rotating the valve 390 to chuck the gear, move the workhead into operating position and clamp it there. In the first part of this movement, the detent 445 rides on the bottom wall 452 of the cam-groove 451. When the handle has been moved through the angle *a* (Fig. 12), the gear will be chucked. At this point, however, the detent 445 will strike the edge of the projection 453 which aids in defining the cam-path 451. This will cause a momentary halt in the rotation of the valve. If the gear, when chucked, does not have its tooth spaces in alignment with the grinding wheel, the operator can swing the handle of the valve back to release the chuck. When the operator is satisfied with the position of the gear, which may be determined by a stock-dividing gauge of any suitable construction, he continues to press the handle toward the left and the detent 445 drops along the edge 454 of the cam-track under actuation of the spring 446 until it strikes the bottom-wall 455 of the cam-track. The operator will now be able to rotate the valve further in the counter-clockwise direction.

When the detent strikes the side wall 456 of the cam-path, it is again stopped. During the movement along the bottom-wall 455, however, the handle has been swung through the angle *b* and the workhead will have been moved to operating position. The operator can not now rotate the valve handle further until he pulls upwardly on the knob 448 to lift the detent upwardly in the portion 457 of the cam-track. This requires a positive act on the part of the operator and insures that the workhead will not be clamped until it has actually been moved wholly into operating position. The operator then swings the handle on through the angle *c* to effect clamping of the workhead. In this movement, the detent travels over the bottom wall 458 of the cam-path 451.

To provide against accidental backward movement of the handle, a recess 459 is formed in the cam-path and the detent 445 is adapted to engage in this recess when the handle is released at the end of its counter-clockwise movement.

Inasmuch as the upper surface 460 of the projection 453 is at the same radial distance from the axis of the valve 390 as the wall 458 of the cam-path, the handle can be swung back in the clockwise direction with a single motion and without stoppage. Thus, the operation of releasing the workhead, moving it out to loading position and dechucking the ground gear can be done with a simple sweep of the hand and without any stopping or delay, the operator simply disengaging the detent 445 from the notch 459 by lifting the knob 448 and then swinging the handle back in a clockwise direction. There is no need for insuring that each operation has taken place before the next operation takes place when the handle is being rotated in the clockwise direction, but it is necessary to insure that the gear is chucked properly before the workhead is moved in and that the workhead is in operative position

before it is clamped and this is the reason why the cam-path is so formed as to stop the movements of the valve at predetermined points in its counter-clockwise rotation.

5 *Dressing mechanism*

The mechanism for dressing the grinding-wheel is, it is believed, unique with the present invention. The dressing mechanism is carried 10 by a member 470 (Figs. 1, 2, 3, 6, 21, and 22) which has the general form of a hollow drum. This member is adjustably mounted on the upright or column 31 for lateral adjustment thereon, the column being formed with the plane surface 15 guideway 472 and the drum 470 being provided with an arm 473 which slides on this guideway and which is provided with a down-turned end 474 that engages over the edge of the guideway to hold the drum against sidewise displacement. 20 The drum is adjusted on the guideway 472 by rotation of the screw-shaft 475. It is secured in any adjusted position by T-bolts 465 which engage in the T-slot 466 cut into the upper face of the guideway 472 and by the T-bolt 467 which engages in the T-slot 468 cut in the front face of the column 31.

The shaft 475 is rotatably mounted in bracket 476 which is secured to the column 31 by screws 477. The shaft threads into a nut 478. This 30 nut is mounted in an arm 479 that is integral with the drum 470 and projects from one side thereof. The nut has a square end-flange 480 (Fig. 21) that is received in a correspondingly shaped recess in the bore of the projection 479 35 so as to hold the nut against rotation and the nut is secured against endwise movement by another nut 482 which threads onto the nut 478 and abuts against the outer end of the projection 479.

40 The screw-shaft 475 is mounted on anti-friction bearings 483 in the bracket 476 and there is a graduated dial 484 secured to the shaft 475 by a set-screw 485. This dial permits of accurate adjustment of the drum laterally on the column 31 45 for a purpose which will hereinafter appear. Telescoping guards 486 are provided between the brackets 476 and the projection 479 to protect the screw-shaft against dirt and grit.

There is a depending bracket or arm 490 50 mounted in the lower end of the drum 470 for rotatable angular adjustment relative thereto. This arm or bracket has a base-portion 491 at its upper end which seats against the lower end of the drum 470 and which is formed with a 55 collar 492 that fits into the bore of the drum so that the bracket 490 can be swiveled angularly in the drum. This angular adjustment is for the purpose of positioning the side dressing tool, which is carried by the arm 490, in correct relation to the grinding wheel to dress the correct pressure angle on one side of the wheel, as will hereinafter appear. For the purpose of effecting this adjustment accurately, the base 491 of the bracket is provided with a lug 494 at one 60 side which carries a scale 495 that reads against a scale 496 secured to a lug 497 formed on one side of the drum 470. The bracket 490 is secured in any position of its adjustment on the drum 470 by bolts 500 (Figs. 1 and 21) which 65 pass through an arcuate slot in the base 491 and thread into the drum 470.

The bracket 490 carries at its lower end a cylinder 505. This cylinder is held in a hole in the bracket 490 by bolts 504. There is a 70 75 ton 506 reciprocable in the cylinder 505 and there

is a piston-rod 507 secured to the piston 506 by a nut 508. The casting comprising the cylinder 509 is so formed as to provide at 509 a guide or bearing for the piston-rod. One end of the piston-rod extends beyond the end of this guide and carries a cup-shaped head 510 which is secured against a shoulder formed on the piston-rod by a nut 511. The head 510 is formed with an arm or projection 512 at one side which is shaped at its outer end to provide split-clamp 513 (Fig. 23). A diamond dresser holder 514 is mounted in this split-clamp. The diamond carried by this holder is used to dress the inside surface of the grinding wheels.

There is a cam-bar 515 secured to the upper 15 side of the head 510. This cam-bar is angularly adjustable on the head 510 having a lug or tongue 516 that engages in an arcuate slot 523 (Fig. 24) cut in the head. It is secured to the head by a bolt 517 that passes through an arcuate slot 518 formed in the cam-bar and that threads into the head.

A guard 519 which is secured to the cylinder 505 telescopes in the head 510 (Fig. 21) to guard against entry of dirt or dust into the cylinder. 25 Fluid under pressure may be supplied to one side of the piston 506 through a duct 520 which is connected to the end cap 521 which closes one end of the cylinder. This end cap is secured to the cylinder by screws 522. Fluid under pressure is admitted to the opposite side of the piston 506 through a duct 524 which is also connected to the end-cap 521 and which communicates with a duct 525 drilled in the cylinder-wall. The piston 506 is held against rotation in 30 the cylinder by an arm 526 that is keyed to the piston-rod 507 and engages in a longitudinal slot 528 formed in a plate 529 that is secured by screws 530 to projections (not shown) on the cylinder 505. 531 designates an oil tight cover 40 for the cylinder.

There is a sleeve-like member 540 (Figs. 21 and 22) mounted in the drum 470 for rotatable adjustment therein. This member is provided with a flange 541 which seats on the upper end 45 face of the drum. The flange has a projection 535 at one side that is graduated on its periphery as indicated at 536 (Fig. 1) and these graduations read against graduations 537 carried by a projection 538 of the drum 470, whereby the 50 sleeve 540 may be adjusted accurately in the drum for a purpose which will hereinafter appear. The sleeve is secured in any position of its angular adjustment on the drum by bolts 543 which pass through arcuate slots in the flange 55 541 and thread into the drum. These bolts 543 also serve to hold the plate 549 in position. This plate serves as a cover-plate for the drum.

There is an arm 542 pivotally mounted in the sleeve 540. The stud or shaft 544 serves to support it in the sleeve. This stud or shaft is journaled on anti-friction bearings 545 and 546 in the sleeve 540. The bearings are held in position by nuts 547 and 548, respectively, which are threaded on the shaft 541 at opposite ends thereof. The arm is formed with a split-clamp at its upper end by means of which and the bolts 543 it is clamped to the stud or shaft 544.

The arm 542 terminates at its lower end in a stud 550. Clamped to this stud by a split-clamp 551 and a bolt 552 is an arm 553 (Figs. 23 and 24) in which is mounted the diamond holder 554. This holder carries the diamond which is used to dress the outside surface of the grinding-wheel W.

The arm 542 is formed with a lug or projection 558 (Figs. 22 and 23) at one side that is shaped to provide a split-clamp. A stud 555 is held in this clamp when the bolt 556 is tightened. This 5 stud is formed on its lower end to provide a contact-member or follower 557, the purpose of which will hereinafter appear.

There is a stud 560 secured to the exterior of the drum 470 by screws 561. This stud serves 10 as a pivot for an arm 562 (Figs. 3, 21, and 22), the arm being rotatably mounted on the stud by means of anti-friction bearings 563 and 564. An end-cap 565 which is secured to the arm 562 by screws 566 serves to protect the bearings 15 against entry of dirt or grit and the bearings are held in position by a nut 567 which is threaded on the stud 560.

The arm 562 is bored at its lower end to receive a rod 570 that is adjustable longitudinally 20 in the bore of the arm. The rod 570 is held against rotation in the bore 571 by a key 572 and it is adjustable longitudinally in the bore 571 by rotation of the screw-shaft 574. This shaft has threaded engagement at one end with the rod 25 570 and is rotatably mounted in a bearing 575 which is secured in any suitable manner to the arm 562.

The rod 570 is of reduced diameter at its outer 30 end and has a support 576 secured to it by means of a split-clamp. There is a diamond holder 578 mounted in the member 576, the member 576 being formed to provide a split-clamp which receives this diamond holder and this second split-clamp being tightened by a bolt 579 (Fig. 23).

35 The diamond mounted in the holder 578 is for the purpose of dressing the tip of the grinding wheel. The longitudinal adjustment of the rod 570 enables the end-dresser to be positioned relative to the side dressers 514 and 554 so as to 40 dress the grinding wheel to the desired point-width. For the purpose of accurate adjustment of the end dresser, a micrometer dial 580 is provided (Fig. 22). This dial is keyed to the screw-shaft 574 and is held against longitudinal movement 45 relative thereto by the nut 581 which is threaded on the outer end of this shaft.

The arm 562 is formed at one side with a projecting portion that terminates in a split-clamp 585 (Figs. 22, 23, and 24). There is a stud 586 50 secured in this split-clamp by the bolt 587. This stud is formed at its lower end with a spheroidal-shaped follower 588 that is adapted to engage the cam-guide 515 which is secured to the head 510 carried by the piston-rod 507 as above described.

There is a cam-guide also secured to the arm 562. This cam-guide is designated at 590. In the embodiment shown, this cam-guide is provided with a straight guide-surface 591. The 60 cam-guide is mounted on the arm 562 for angular adjustment thereon. It is formed with a tongue 592 on its under-face which engages in an arcuate slot 593 in the upper face of the seat on the arm 562 on which the cam-bar is mounted. The 65 cam-guide is secured in any adjusted position by a bolt 594 which passes through an arcuate slot 594' in the cam-guide and threads into the arm 562.

The follower 557 carried by the arm 542 engages 70 the cam-surface 591 of the cam-plate 590. This follower is held constantly in engagement with the cam-surface 591 by action of a spring-pressed plunger 595. This plunger is housed in a bore formed in a lug 596 that is integral with 75 the sleeve-member 540. The plunger engages at

its upper end a hardened stud 597 that is fastened in the tail-part 598 of the arm 542. The plunger 595 is constantly urged upwardly by the coil-spring 599. The upward movement of the plunger is limited by the nut 601 which is 5 threaded on the lower end of the plunger.

From the preceding description, it will be seen that as the piston 506 is reciprocated, the diamond carried by the holder 514 will be reciprocated along the side I of the grinding wheel W to 10 dress the inside surface of the grinding wheel and that simultaneously the arm 562 will be swung about the axis of the shaft 560 through contact of the follower 588 with the cam 515, thereby causing the end-dresser 578 to be swung across 15 the tip surface T of the grinding wheel to dress the same; and that simultaneously the arm 542 will be swung about the axis of the shaft 544 because of contact of the follower 557 with the cam 590 so that the diamond carried by the holder 20 554 will be swung across the outside surface O of the grinding wheel to dress the outside surface of the wheel. Thus all three diamonds are 25 actuated by movement of the single piston 506.

The distance of the diamond holder 554 from 30 the shaft 544 is relatively so great that the diamond in the holder swings on an arc that for the length of the outside surface O of the grinding wheel approaches very close to a straight line. Hence, the outside surface of the grinding wheel 35 will be dressed with sufficient accuracy for all practical purposes.

The movement of the piston 506 is controlled from a manually operable valve 605. This valve is operated by a knob or handle 606 (Figs. 1 and 35 22). The valve slides in a sleeve 607 that is secured in a casting 604 which is fastened in any suitable manner to the column 31. Fluid under pressure is supplied to the valve 605 through the duct 608 and the radial ports 609 formed in the 40 sleeve 607. Fluid is exhausted from the valve through the radial ports 610 and 611 formed in the sleeve 607 adjacent opposite ends thereof. These ports communicate with ducts 612 and 613, respectively, that are connected with a duct 45 614 which leads back to the sump. The valve is connected to the lines 520 and 524 which lead, respectively, to opposite sides of the piston 506, by the radial ports 616 and 618, respectively, in the sleeve 607. 50

The valve 606 is normally held in its upper position by the coil-spring 619 which is interposed between the bottom of the valve and the valve housing. In this position, the dressers are withdrawn. When the operator presses down 55 on the knob 606 the dressers are moved to effect passage in one direction across the grinding wheel. When the operator releases the knob 606, the valve returns to its upper position and the dressers make a passage in the reverse direction 60 across the grinding wheel.

The grinding wheel is not dressed in its operative position but is swung up out of operative position in order to dress it. In other words, the dressing mechanism is fixed relative to the grinding wheel. This is for the purpose of greater accuracy in the dressing of the wheel and insures that the correct pressure angles will be dressed on opposite sides of the wheel. 65

Mechanism for swinging grinding wheel to dressing position 70

To swing the grinding wheel up into dressing position, the operator rotates the lever 625 (Fig. 4) in a counter-clockwise direction. This lever 75

is keyed to a stud 626 which is journaled in a bearing 627 that is secured in any suitable manner in the guard 628. This guard is fastened in any suitable manner to the column 31. The inner 5 end of the shaft 626 is connected by a link 630 with the head of a reciprocable valve 632. The valve 632 is mounted to reciprocate in a sleeve 634 which is secured in a casting 636. This casting is fastened in any suitable manner to one side 10 of the column 31.

The valve 632 controls the movements of a piston 638 which reciprocates in a cylindrical bore 639 formed in the casting 636. A piston-rod 640 is secured to the piston 638 by a nut 641. 15 This piston-rod extends upwardly through a guide-member 642, that is secured in the bore 639, and through the cap-member 643 which closes the upper end of the bore 639.

The piston-rod 640 is threaded at its upper end 20 beyond the point where it extends through the cap-member 643. The threaded portion of the rod engages in a split-nut 645, which is, therefore, adjustable longitudinally on the rod and which is clamped in any adjusted position by tightening 25 up the bolt 646 to tighten the nut around the rod. The nut 645 is formed as a projection on a plate 647 that is secured by screws 648 to a plate 649 that is reciprocable in a guide-way formed in the casting 636 at one side thereof, 30 (Figs. 4 and 25). The adjustment of the plate 649 with reference to the piston-rod 640 permits of angularly adjusting the path of swing of the grinding-wheel so as to grind gears of different spiral angles, as will hereinafter appear.

35 The plate 649 is recessed on one side at its upper end and in this recess there is mounted a rack 650. This rack is secured to the plate 649 by screws 651 and it meshes with a segmental gear 652 (Figs. 4 and 5). This gear is secured 40 by screws 653 to the differential housing 138.

Fluid under pressure is supplied to the valve 632 through the duct 655 and the radial ports 656 in the valve-sleeve 634. The motive fluid is exhausted from the valve either through the 45 radial ports 658 and the duct 659 or through the radial ports 660 and the duct 661. The pressure fluid is admitted to the upper face of the piston 638 through the radial ports 662 in the valve sleeve 634 and the duct 663. It is admitted to the lower face of the piston through the radial 50 ports 664 and the duct 665.

The position of the piston 638 during grinding of a gear is shown in Fig. 4. The piston is in its lowermost position and is held against 55 movement by the pressure of the motive fluid upon its upper face. Thus, the differential housing 138 (Fig. 5) is held against rotation and the grinding wheel swings back and forth in its working path, the drive being from the crank 120 through the connecting rod 127, link 130, gears 140, 141, 142 and 148, the gear 155 and the segmental gear 156 (Fig. 5).

When the operator desires to dress the grinding wheel he first stops the swinging motion of 60 the grinding wheel by pressing a stop-button (not shown) to stop the drive motor 105. He then rotates the lever 625 in a counter-clockwise direction to move the valve 632 downwardly. This 65 puts the upper side of the piston 638 on exhaust and the under side of this piston on supply. Thus the rack 650 is moved upwardly, rotating the segmental gear 652 to rotate the differential housing 138, gear 155 and segmental gear 156 to swing the grinding wheel up out of its working path 70 into dressing position. When the dressing opera- 75

tion is completed, the grinding wheel is returned to operative position by rotating the handle 625 back in the clockwise position.

As above indicated, the working path of the grinding wheel is adjustable angularly about the 5 axis of swing of the wheel in order to grind gears having teeth of different spiral angles. The wheel is always swung to the same position, however, for dressing, regardless of the angular position of its working path. This result is obtained because a stop 667 (Fig. 4) is provided on the quill 34 and the piston 638 moves upwardly under hydraulic pressure, when the valve 632 is shifted, until this stop contacts the stop 668 secured in the arm 50. Thus the stop 668 15 serves as a limit stop for the upward swinging movement of the quill and the wheel is always swung upwardly to the same position for dressing regardless of the position of its working path. 20

Clamping mechanism for the wheel head

Before dressing the grinding wheel, it is usual 25 for the operator to advance the grinding wheel toward the work a distance determined by the amount of stock to be removed from the grinding wheel in the dressing operation. To advance the wheel, the operator first releases the T-bolts 670 (Fig. 2) which clamp the wheel head 32 to the column 31 and then he rotates the shaft 672 (Figs. 1 and 6) to advance the wheel 30 toward the work.

There are four T-bolts 670 placed at the four corners of the head 32 to bolt the head on the column 31. The T-bolts at the front and rear at one side of the machine engage in a longitudinal T-slot 674 cut into the upper face of the column 31 and the T-bolts at the opposite side of the machine engage in parallel longitudinal T-slots. 35

Each of the T-bolts is secured to a piston 675 40 that is moved to clamping position by fluid pressure on its under face and that is moved to released position by a coil-spring 676. The spring 676 is interposed between the upper face of the piston and a cover plate 677. The cover plates 45 677 are secured to the upper face of the head 32 by screws 678 (see Fig. 6). One of the cover plates is shown removed in this figure.

The positions of all four of the T-bolts are controlled from a single reciprocable valve 680. 50 This valve is normally pressed upwardly to the position shown in Fig. 2 under actuation of a coil-spring 681 which is interposed between the bottom face of the valve and a plate 682 that closes the lower end of the bore in which the valve 55 reciprocates. The valve is connected with the lower face of each one of the pistons 675 by ducts 683, only one of these ducts being shown in Fig. 2. Pressure fluid is supplied to the valve through a duct 684 and exhausted through a duct 685. 60

The valve is manipulated by a lever 686 which is pivoted by the pin 687 between ears 688 formed on the cover-plate 689. This plate is secured to the plate or head 32 by screws 690 (Fig. 6). The upper end of the valve 680 projects through an opening in this cover-plate and contacts the under face of the lever 686. In the position shown, the lines 683 are on supply and the head 32 is clamped to the column 31. When the operator presses down on the lever 686 he depresses the valve 680 against the resistance of the spring 681, putting the lines 683 on exhaust. This allows the springs 676 to release the T-bolts and the head 32 can then be adjusted on the column 31. 70 75

Adjustment of wheel head

To adjust the head on the column, the operator rotates the shaft 672, as stated above. This shaft is journaled in a bracket 692 (Fig. 6) and in a bearing 693 formed in the head 32. The bracket 692 is secured to one side of the head 32 by screws 694. Secured to the inner end of the shaft 672 is a bevel pinion 694. This meshes with a bevel gear 695 that is keyed to a screw-shaft 696. This shaft is journaled in a suitable bearing in the head 32 and in a cap-member 697 that is secured to the head 32 by screws 698. The shaft 696 is threaded for a portion of its length, having engagement with a nut 699 which is secured to the column 31 by screws 700. To permit accurate adjustment of the head 32 on the column, a micrometer-dial 702 is provided. This dial is secured to the shaft 672 by a set-screw 703.

Operation of semi-automatic machine

The use and operation of the semi-automatic machine will be obvious from the above description but will be summed up briefly here.

First of all, the operator adjusts the machine to position the grinding wheel, work and dressing mechanism in accordance with the spiral angle, cone-distance and pitch cone angle of the gear to be ground.

The work is adjusted for spiral angle by vertical adjustment of the work spindle carrier 221 on the column 225 (Fig. 7) and by lateral adjustment of the plate 270 on the frame or bed 30. The vertical adjustment is effected by rotation of the shaft 226, while the lateral adjustment is effected through rotation of the screw-shaft 276 (Figs. 1 and 7). The latter shaft is rotatably mounted in the bracket 329 and threads into a nut (not shown) that is secured to the plate 270.

The grinding wheel is adjusted so that its working path will be symmetrical with reference to the tooth being ground, as determined by the spiral angle of the gear, by loosening the split-nut 645 (Fig. 4) and rotating the screw-shaft 641. This moves the rack 650 vertically to adjust the position of the quill 34 (Figs. 2 and 4) angularly through operation of the gears 652, 155 and 156. After the adjustment is made, the bolt 646 is tightened up again. Thus the angular position of the path of swing of the grinding wheel is predetermined in accordance with the spiral angle of the gear to be ground.

It is not necessary to adjust the dressing mechanism to correspond to the spiral angle of the gear to be ground, for the grinding wheel always comes to the same position for dressing as above described.

The workhead is adjusted for cone distance by loosening up the nut 247 (Fig. 11) and rotating the screw-shaft 243 and then tightening the nut again. The workhead is adjusted to the correct root angle by swinging the base 235 (Figs. 7 and 11) on the plate 270, the base 235 being secured to the plate 270 after adjustment by the bolts 274.

The dressing mechanism is adjusted for diameter, pressure angle and point-width of the grinding wheel. For diameter, the dressing mechanism is adjusted radially of the grinding wheel by rotation of the screw-shaft 475 (Fig. 21). For the pressure angle desired on the inside surface of the grinding wheel, the arm 490 is adjusted angularly on the drum 470. This adjustment is effected by loosening up the bolts 500 and rotatably adjusting the arm 490 on the drum, the adjustment being made accurately by use of the

graduations 495 and 496 (Fig. 1). For the correct pressure angle on the opposite side of the wheel, the arm 542 carrying the outside diamond is adjusted angularly on the drum 470 by rotation of the sleeve 540 in the drum. This is done by loosening up the bolts 543 (Fig. 21) and rotating the sleeve 540 in the drum, the drum and sleeve being provided with cooperating graduations, as indicated at 536 and 537 (Fig. 21). The end dresser 578 (Fig. 24) is adjusted relative to the 10 point of intersection of the paths of the side dressers 514 and 554 in order to determine the point-width to be dressed on the wheel. This is effected by rotation of the screw-shaft 574 (Fig. 22).

Before starting the machine, the operator also adjusts the appropriate feed-cam track 201 or 202 into engagement with the follower 45 (Fig. 2) depending upon whether the gear is to be rough or finish ground. It is usual to take one or more rough grinds on a gear and then finish-grind it. The cam 200 carrying the two tracks 201 and 202 can be adjusted by rotation of the handle 205.

When all of the adjustments have been made the operator mounts the gear G to be ground 25 on the work spindle and places the clamping disc 369 (Fig. 1) over the head of the draw-bar 365 in position to engage the gear and clamp the same when the draw-bar is drawn back in the work spindle. The workhead is at this time, of course, in loading position with the chucking mechanism in released position.

The operator now rotates the valve-handle 440 (Fig. 11) in a counter-clockwise direction. The handle moves freely through the angle a (Fig. 35 12) until the detent 445 strikes the ledge 453 defining the cam slot 451. During this portion of the movement, the left-hand end of the cylinder 381 (Fig. 11) will have been placed on exhaust and the spring 366 will operate to chuck the work. 40 If the tooth-spaces of the gear are correctly aligned with the grinding wheel the operator allows the detent 445 to drop down onto the wall 455 of the cam-slot. This allows continued movement of the handle 440 in the counter-clockwise 45 direction. If a tooth space of the gear does not line up correctly with the grinding-wheel, the operator rotates the handle 440 back to starting position in order to dechuck the gear again so that he can rotate the gear angularly on the 50 work spindle to correctly line a tooth space up with the grinding-wheel.

When the gear is satisfactorily chucked, the operator rotates the handle 440 on in the counter-clockwise direction to put the line 434 (Fig. 11) 55 on supply and the line 435 on exhaust to move the work into operating position. This occurs during the swing of the handle 440 through the angle b (Fig. 12). The detent 445 then strikes the side-wall 456 of the cam slot. To clamp the 60 workhead in operative position, the operator must then pull up on the knob 448 of the handle 440 to lift the detent 445 up in the portion 457 of the cam-slot. This enables the operator to swing the handle 440 on in the counter-clockwise direction to place the line 431 leading to the cylinder 264 (Fig. 10) on exhaust and the line 430 on supply. Thus, the workhead clamp jaws 251—258 are actuated to clamp the workhead in operative 65 position.

The motor which drives the grinding wheel is started when the work is chucked, the switch 387 (Fig. 11) controlling this latter motor. When the work is in operating position, the operator starts the main drive motor 105 (Fig. 1). The 70 75

grinding wheel thus rotates on its axis and simultaneously swings back and forth in a circular arc about the axis of the shaft 92 (Fig. 2). As the grinding wheel rotates and swings it is fed into a tooth space of the gear under actuation of the feed cam 200, this cam engaging the follower 45 and moving the whole quill 34 longitudinally in a direction axial of the shaft 92. As the grinding wheel feeds into depth it grinds the sides of a tooth space of the gear. After the wheel has reached full depth position it is withdrawn, the spring 65 (Fig. 2) holding the follower 45 against the cam 200 and causing the withdrawal. When the wheel has cleared the work, the gear is indexed through operation of the cam 310 (Figs. 1 and 5) which actuates the index mechanism. This cam rotates in timed relation with the feed cam as above described. As soon as the indexing is complete, the feed cam operates to feed the grinding wheel back into the gear to grind a new tooth space of the gear. The alternate feed for grinding and withdrawal for indexing proceed until all of the tooth spaces of the gear have been ground. Then the machine stops automatically.

The stop mechanism may be of any usual or suitable construction. A device may be used, for instance, such as disclosed in the patent to Ford, No. 1,908,626 of May 9, 1933, and the use of such a stop-mechanism is illustrated in the accompanying drawings, the automatic stop mechanism being indicated at 710 in Fig. 1. This stop mechanism may be operated from a cam 711 (Fig. 5) which is secured to the shaft 311 by a set-screw 712. This cam will rotate in time with the feed cam 200 and the index cam 310.

The usual practice is to take at least one rough-grind around the gear and then finish-grind it. When the machine stops automatically, as described, after the rough-grinding operation, the workhead does not have to be withdrawn to loading position, but is kept in operative position until the gear has been finish-ground.

It is the usual practice to dress the grinding wheel between the rough-grinding operation and the finish-grinding operation. To dress the grinding wheel, the operator first swings the grinding wheel up out of its working path by rotating the lever 625 (Figs. 1 and 4) in a counter-clockwise direction to cause the piston 638 to move the rack 650 upwardly and swing the quill 34 to dressing position.

Before dressing, the operator will usually advance the grinding wheel a distance determined by the amount of stock he wishes to remove in the dressing operation. To do this, he unclamps the head 32 from the column 31 by depressing the handle 686 (Figs. 1 and 2) and then advances the head 32 by rotating the shaft 672 (Figs. 1 and 6), as above described.

The operator then dresses the grinding wheel by depressing the knob 606 (Figs. 1 and 22). This causes the piston 508 to be moved to the right from the position shown in Fig. 22, passing the side dresser 514 across the inside surface of the grinding wheel and simultaneously moving the end dresser 578 across the tip of the grinding wheel and swinging the side dresser 554 across the outside surface of the grinding wheel through operation of the cams 515 and 590, respectively, and the cam-followers 586 and 587, respectively. Release of the handle 606 allows the valve 605 to be shifted upwardly again by action of the spring 619 and causes return of the dressers to original position.

After the wheel has been dressed, it is swung back into operative position again by rotating the handle 625 (Figs. 1 and 4) back in the clockwise direction. Before starting the machine again, however, the operator will shift the cam shaft 195 (Fig. 2) to move the roughing feed-cam track 202 out of operative engagement with the follower 45 and bring the finishing feed-cam track 201 into operative position. This he does by rotating the handle 205 (Fig. 1) to rotate the pinion 206 (Fig. 2).

The machine is then started again and the tooth spaces are finish-ground in the same manner as already described. When all of the tooth-spaces have been finish ground, the machine again stops automatically. Then the operator can unclamp the workhead, withdraw it and dechuck the gear by rotating the handle 440 (Figs. 1 and 11) back in the clockwise direction.

Fully automatic machine

The fully automatic machine may be similar in construction to the semi-automatic machine described, and for this reason it has not been considered necessary to illustrate the fully automatic machine in detail. Only those parts have been shown which are of different construction or are differently operated in the automatic machine and the diagram of Fig. 30 it is believed will, in connection with the figures showing these parts, indicate clearly how the automatic machine may be constructed and operate.

In the automatic machine, the adjustments of the work, grinding wheel and dressing mechanism, respectively, are the same as in the semi-automatic machine. The valve which controls the chucking mechanism, movement of the workhead from loading position to operating position and vice versa, and the clamping of the workhead in operating position may be of the same construction as the valve employed on the semi-automatic machine and is so illustrated. To insure that the gear is correctly aligned with the grinding wheel before it is moved into operative position and to insure that the workhead is actually in operating position before it is clamped, this valve is arranged to be manually rotated in one direction (the counter-clockwise direction) just as it is in the semi-automatic machine. Means is provided, however, for operating this valve automatically in the reverse direction so that when the gear has been completely ground, the workhead will be released, moved to loading position and the gear dechucked automatically.

Means is also provided for moving the grinding wheel automatically to dressing position after the rough grinding operation and for dressing the wheel automatically between the rough and finish grinding operations. In this connection, also, means is provided for automatically unclamping the grinding wheel head from the supporting column and for advancing the grinding wheel prior to the dressing operation and for clamping the head again after its advancement. Means is also provided for automatically shifting the feed-cam shaft between the rough and finish grinding operations so as to move the roughing cam out of operative position and bring the finishing cam into operative position prior to the finish grinding operation. After the wheel has been dressed, the wheel will be returned to dressing position and the machine restarted automatically.

Those parts, which may be used in the fully automatic machine and be of identical construction with parts employed in the semi-automatic

machine, are designated by the same reference numerals as were used to denote them in the description of the semi-automatic machine.

The valve for controlling chucking, movement 5 of the workhead to and from operative positions and clamping of the workhead has in the fully automatic machine again been designated at 390 (Figs. 27 and 36). A cam-plate 720 (Fig. 28) similar to the cam-plate 450 (Fig. 12) may be 10 used to control the movement of this valve 390 in the fully automatic machine. The only difference between the cam-plate 720 and the cam-plate 450 is that at the end of the cam-path in which the detent 445 travels, there is 15 a recess 721 in which the detent 445 is resiliently held at the end of the counter-clockwise movement of the handle 440. The shaft 722 (Fig. 27) to which the valve 390 is keyed in the fully automatic machine is elongated and passes 20 through an opening in the end-plate or bracket 724. Beyond this opening, the shaft 722 is provided with a collar 725 and a coil-spring 726 is interposed between this collar and the outside face of the bracket 724. It is this coil-spring that 25 retains the detent 448 in the recess 721 during grinding. The brackets 724 and 723 serve for mounting the valve on the machine.

A coil-spring 727 is provided to automatically rotate the shaft 722 and valve 390 back in the 30 clockwise direction when the detent 445 is released from the recess 721, thereby to return the valve and automatically release the workhead, move it to loading position and dechuck the completed gear. This coil-spring is secured at one 35 end to the shaft 722 and at its other end to a relatively stationary part of the machine.

The detent 445 is automatically disengaged from the recess 721 when the grinding operations 40 on a gear have been completed. This is accomplished by automatically energizing a solenoid 730 in a manner which will hereinafter be described. The solenoid controls movement of a core-bar 731 that is pivotally connected at 732 with a lever 733. This lever is pivotally mounted at 734 on 45 the bracket 724. It carries at a point intermediate its length a pin 735 which engages in a groove 736 turned in the shaft 722. Hence, when the solenoid is energized, the shaft 722 is shifted to the left, disengaging the pin 448 from the recess 50 721 and allowing the coil-spring 727 to return the valve 390 in the clockwise direction.

Some changes are necessary in the feed mechanism in order to adapt the semi-automatic machine for automatic operation. The feed cam-shaft 55 may remain the same as in the semi-automatic machine and is designated at 195 as before. It is journaled on antifriction bearings 196 and 197 in a sleeve 740 (Fig. 31). This sleeve, like the sleeve 198 (Fig. 2) is provided on its periphery 60 with rack-teeth 741 so that it may be adjusted axially. There is a cam-bar 742 adjustably secured to the sleeve 740 by a bolt 743. This bolt passes through a slot 744 in the bearing 50 for the sleeve and threads into the sleeve.

The cam-bar 742 is provided with a plurality of cam-projections designated 745, 746, 747, 748 and 749, respectively, the purposes of which will appear hereinafter. The feed cam 750 is similar to the feed-cam 200, the only difference being that 70 the positions of the roughing and finishing cam-tracks on the cam 750 are reversed with respect to their positions on the cam 200, the roughing cam-track 751 being above the finishing cam-track 752. This inversion of position is because the 75 sleeve 740 is moved vertically upward in shifting

the roughing cam-track out of engagement with the follower 45 and bringing the finishing-cam track into engagement with this follower.

The cam-shaft 195 is rotated by the gear 188 through the same gearing as already described 5 for the semi-automatic machine.

To shift the feed-cams the pinion 207, which meshes with the rack 741, is automatically rotated. This is effected by movement of a piston 755 which reciprocates in a cylinder 756 that is 10 secured to a wheel-head 758. The wheel-head 758 is identical in construction with the wheel-head 32 except for such changes as are necessary in order that it may support the parts herein-after described.

There is a piston-rod 759 secured to the piston 755. This rod projects downwardly through an opening in the head 758. There is a pawl 760 pivotally mounted at 761 on the piston-rod 759. This pawl is adapted to engage a ratchet-member 762 20 which is secured to the shaft 206 on which the pinion 207 is mounted.

The pawl 760 is normally pressed into position to engage the ratchet-member 762 by a spring-pressed plunger 764 which is housed in a bore in 25 the piston-rod 759. A pin 765 is mounted in the column 31 in position to engage the tail of the pawl and disengage the same from the ratchet-member when the piston-rod 759 has travelled a definite distance downwardly, sufficient to shift 30 the cam-shaft 195 the desired amount.

In the fully automatic machine, the T-bolts 35 for clamping the wheel head are hydraulically operated, just as in the semi-automatic machine.

In the fully automatic machine, each of these T-bolts 770 is connected to a piston 771 (Fig. 32). The connection is through a pin 772 on the piston-rod 773 which engages in a longitudinal slot 774 cut in the head of the T-bolt. The four pistons 771 are controlled from a single valve 775 (Fig. 40 36). This valve is connected with opposite ends of each piston 771 by ducts 776 and 777 in a manner such as shown diagrammatically in Fig. 36.

One of the pistons 771 has its piston-rod 773 extending upwardly as well as downwardly and the 45 upper end of this piston-rod extends through an opening in the end-plate 780 of the cylinder 781 in which the piston reciprocates (Figs. 26, 32, and 36). This piston-rod 773 is pivotally connected at its upper end at 782 with a lever 783. The 50 lever 783 is pivotally mounted at 784 between ears 785 formed integral with the end-plate 780. The free end of the lever 783 extends over the outwardly projecting end of a valve 787. This valve controls the movement of a piston 790 (Figs. 29 55 and 36) which operates the screw for advancing the wheel-head, when it is released, as will be described more particularly hereinafter.

The valve 787 reciprocates in a sleeve 791. There is also a second valve 792 reciprocable in 60 this sleeve. The valve 792 is a selector valve determining the rate of movement of the dressers in the dressing operation as will hereinafter appear.

Fluid under pressure is supplied to the valve 65 787 through the duct 793 and the radial ports 794 in the sleeve 791. The motive fluid is exhausted from the valve 787 through the port 795 and duct 796 or through the port 797 and duct 798. The valve 787 is connected with one end of the piston 70 790 through the radial ports 800 in the sleeve 791 and the duct 801. It is connected with the opposite side of the piston 790 through the radial port 802 in the sleeve 787 and the duct 803.

The valve 787 is normally pressed upwardly by 75

a coil-spring 805 which is interposed between the two valves 787 and 792.

As above indicated, the piston 790 operates the mechanism for advancing the grinding-wheel to compensate for wear. The piston 790 is secured against a shoulder on the piston-rod 810 by a nut 811 (Fig. 29). The piston-rod 810 extends downwardly through an opening in the lower end-wall of the cylinder 812 in which the piston 790 is reciprocable. The piston-rod carries a pawl 813 which is adapted to engage a ratchet-wheel 814 that is secured to a screw-shaft 815 (Fig. 26). The screw-shaft threads into the nut 699 (Figs. 5 and 24) which is secured by the screws 700 to the column 31. The screw-shaft is journaled in a bearing 816 formed integral with the plate or head 768 and in a bearing 817 which is secured to this head by screws 818. The pawl 813 slides in a pocket 820 which is secured in one side of the piston-rod 810. It is resiliently held in engagement with the ratchet-wheel by a coil spring 821 which is interposed between the pawl and the bottom of the cup or pocket 820. The pawl 813 is secured to a stem 822 which has a head 823 that has a rounded bottom.

The stem 822 of the pawl 813 extends through a slot 824 in a rod 825. This rod 825 is longitudinally slideable in a bore in the piston-rod 810. The rod 825 carries at its lower end a cam-member 826 which has an inclined outer surface 827 adapted to straddle the stem 822 of the pawl 813 to disengage the pawl from the ratchet-wheel 814 when the rod 825 is moved upwardly. The cam-member 826 is secured to the rod 825 by a screw 828.

To disengage the pawl 813 from the ratchet-wheel 814, the operator rotates the collar-member 830. The rod 825 passes through a bore in this member and the head of the rod engages against the upper face of this member. The under face of this member is cam-shaped as indicated at 832 and engages the correspondingly cam-shaped upper end face of the piston-rod 810 so that when the collar 830 is rotated in one direction, the rod 825 will be pulled upwardly to disengage the pawl 813 from the ratchet-wheel. When the pawl is disengaged the head or plate 758 may be adjusted manually on the column 31 through manual rotation of the screw-shaft 815.

The amount of movement of the screw-shaft 815 during the automatic operation of the machine, that is, the amount of advance of the wheel-head automatically, may be adjusted by rotation of the nut 835 (Fig. 29) which threads into the head 758. This nut determines the amount of stroke of the piston 790 since it serves in any adjusted position as a limit-stop to the upward movement of the piston.

In its movements, the piston-rod 810 shifts a valve 836 (Figs. 29 and 36) which controls the movement of the piston 506 that operates the dressing mechanism. A lever-arm 837 is pivotally mounted at 838 in the column 31. It is this lever-arm which transmits the movement of the piston-rod 810 to the valve 836. One end of this lever engages the stem 839 of the valve 836 and the other end of the lever is positioned to enter a recess 840 in one side of the piston rod 810. Thus, as the piston-rod 810 travels in one direction or the other, one of the side-walls of the recess 840 will strike the short end of the lever 837, swinging this lever about its pivot 838 and either shifting the valve 839 upwardly or allowing it to move downwardly by action of gravity,

depending upon the direction of movement of the piston-rod 810.

Fluid under pressure is supplied to the valve 836 through the duct 842 and the radial ports 843 in the sleeve 844 in which the valve slides. The motive fluid is exhausted from the valve either through the radial ports 845 in the sleeve 844 and the duct 846 or through the radial ports 847 in the sleeve 844 and the duct 848. The valve 836 is connected with one side of the piston 506 through the ports 849 in the sleeve 844 and the duct 520. It is connected with the opposite side of the piston 506 through the ports 851 in the sleeve 844 and the duct 524. Thus the valve 836 controls the direction of movement of the piston 506.

The two exhaust ducts 848 and 846 from the valve 836 are connected externally of the valve-chamber to form a single exhaust duct 855. The rate of movement of the dressers in dressing the grinding wheel is determined by throttling the flow of the exhaust fluid from this line. To this end, a pair of separately adjustable throttle-valves 857 and 858 (Fig. 33) are provided. These valves thread into the housing 860 (Fig. 32) of the valve 792 and are adjustable by rotation. One valve 858 is intended to be operative when the wheel is being dressed prior to a rough-grinding operation and the other valve 857 is intended to be operative when the wheel is being dressed prior to a finish-grinding operation. The selector valve 792, previously mentioned, determines which one of the valves 857 and 858 is operative at a given time. The exhaust line 855 is connected to the valve 792 through the radial ducts 862 in the sleeve 791. Radial ports 864 in the sleeve 791 communicate with the port 865 controlled by the throttle valve 857 and radial ports 866 in the sleeve 791 communicate with the port 867 controlled by the throttle valve 858. The ports 865 and 867 are connected with a single exhaust duct 868 that leads back to the sump of the machine.

The selector valve 792 is normally held in the position shown in Figs. 32 and 36 by the coil-spring 805. In this position the flow of the exhaust fluid from the valve 836 (Figs. 29 and 36) is through the line 855, the ports 862, the ports 866 and the throttle-valve 858 to the exhaust line 868. In this position, therefore, the rate of movement of the dressing diamonds across the grinding wheel is determined by the setting of the throttle valve 858. This position of the selector valve 792 is the position during dressing of a grinding wheel prior to a rough-grinding operation, and the throttle-valve 858 controls the rate of movement of the diamonds across the grinding wheel during dressing. The throttle valve 858 is ordinarily adjusted to allow of a more rapid movement of the dressers than the throttle valve 857, since it is not necessary to have as smooth a surface on the grinding-wheel for rough-grinding as for finish-grinding.

The selector-valve 792 is shifted automatically prior to dressing of the grinding wheel for a finish grinding operation so as to open the ports 864 and close the ports 866. The shifting of this valve is effected by energizing the solenoid 870. When energized, this solenoid pulls the core-bar 871 upwardly against the resistance of the spring 805, the core-bar being attached to the stem of the valve 792. With ports 866 closed and the ports 864 open, the flow of the exhaust-fluid from the valve 836 (Fig. 29) is through the line 855, ports 862, ports

864 and throttle valve 857 to the exhaust-line 868. Thus, at this stage, the throttle valve 857 determines the rate of movement of the dresser diamonds across the grinding-wheel. By properly 5 adjusting the valve 857, a fine feed of the diamonds may be secured so as to produce a finer surface on the grinding-wheel prior to finish grinding so as to insure the quality of finish on the gear-teeth which is desired.

10 The movement of the piston 755 (Figs. 31 and 36), which shifts the feed-cam, is controlled by the valve 875 (Figs. 30 and 36). This valve reciprocates in a sleeve 876. It is moved in one direction by the solenoid 878, when energized, and 15 in the opposite direction by the coil-spring 879. The coil-spring surrounds the core-bar 880 of the solenoid and it is interposed between a collar 881 formed on the core-bar and a cover-plate 882 which closes the lower end of the bore in 20 which the valve 875 slides. The valve 875 is held between the collar 881 and a second collar 883 also formed on the core-bar so that it moves with the core-bar.

Fluid under pressure is supplied to the valve 875 25 from a duct 884, which is connected to the pressure side of the pump. This duct is drilled into the housing 885 in which the sleeve 876 and valve 878 are mounted. This housing is formed integral with the wheel-head or slide 758. The duct 30 884 leads into a cross-duct 886 in the casting 885 and this cross-duct communicates with radial ports 887 in the sleeve 876.

The motive fluid is exhausted from the valve 875 either through the radial ports 889 in the 35 sleeve 876 or through the radial ports 891 in this sleeve. The ports 889 communicate with a duct 890 in the casting 885 and the ports 891 communicate with a duct 892 in this casting. The duct 890 is connected to the duct 892 by a duct 40 893 and this duct 893 is connected to a duct 894 that leads back to the sump of the machine.

The valve 875 is connected with one side of the piston 755 through the radial ports 895 in the sleeve 876 and the duct 896 (Figs. 30, 31, and 45 36). The valve 875 is connected with the opposite side of the piston 755 through the radial ports 897 in the sleeve 876 and the duct 898.

The movements of the piston 771 (Figs. 32 and 50 36) which control the clamping and unclamping of the wheel-head 758, are controlled, as above described, by the valve 775 (Figs. 30 and 36). This valve is reciprocable in a sleeve 900 which is secured in a bore in the valve-housing 885 that is parallel to the bore in which the sleeve 55 876 is secured. The cover-plate 882 serves to close the lower end of this bore, as well as the lower end of the bore in which the sleeve 876 is mounted. The upper ends of the two bores are closed by a cover-plate 902 (Figs. 26 and 30) which is secured in position by screws 903.

The valve 775 is moved in one direction by the solenoid 904 and in the opposite direction by the coil-spring 905. The coil-spring 905 surrounds the core-bar 906 of the solenoid and is interposed between a collar 907 formed on the core-bar and the cover-plate 882. The valve 775 is held between the collar 907 and a second collar 908 so as to move with the core-bar.

As above indicated, the valve 775 is connected 70 with one side of the piston 771 (Figs. 32 and 36) by radial ports 909 in the sleeve 900 and by the duct 771. The valve is connected with the opposite side of the piston 771 by radial ports 910 in the sleeve 900 and by the duct 776. Fluid under pressure 75 is supplied to the valve 775 from the cross-

duct 886 through the radial ports 912 in the sleeve 900. The motive-fluid is exhausted from the valve 775 either through the radial ports 913 and the cross-duct 890 or through the radial ports 914 in the sleeve 900 and the cross-duct 891. 5

In the fully automatic machine, the movement of the grinding wheel to and from dressing position is effected by movement of the piston 638 (Figs. 4 and 36). In the fully automatic machine, however, the movements of this piston are automatically controlled by automatic shifting of the valve 920 (Fig. 36) which governs the direction of application of fluid-pressure to this piston. The valve 920 is identical in construction with the valve 632 (Fig. 4) except that the valve 920 is 15 connected to the core-bar 921 of a solenoid 922, while the valve 632 is connected to the manual operating lever 625.

The valve 920 reciprocates in a sleeve which is identical in construction with the sleeve 634 20 of Fig. 4 and is designated in Fig. 36 by the same reference numeral. The supply and exhaust lines to the valve 920 are similar to those to the valve 632 and the valve 920 is connected with opposite ends of the piston 638 in the same way as the 25 valve 632 is connected with this piston in the semi-automatic machine. Therefore, in Fig. 36 the same reference numerals will be used to designate the supply and exhaust lines and the connections between the valve 920 and piston 638 30 as were used in Fig. 4 to designate these lines and these connections.

In the fully automatic machine, there is a contact-bar 925 carried by the piston-rod 640, the purpose of which will hereinafter appear. The 35 core-bar 921 of the solenoid 922 also carries a contact-bar which is designated at 926 and the purpose of which will also hereinafter appear.

In Fig. 36, 930 designates the sump of the machine, 931 the pump for supplying the motive- 40 fluid to the various fluid-actuated parts of the machine, 932 a relief-valve for controlling the pressure in the system and 105 the main-drive motor of the machine. This motor may be the same as the motor 105 shown in Fig. 1 and in the 45 fully automatic machine drives the same or a similar train of gearing.

Operation of a fully automatic machine

To use the fully automatic machine, the operator will, of course, first adjust the work, grinding wheel and dressing mechanism, the same as in the semi-automatic machine. Then he will chuck the work, move the workhead into operating position and clamp the workhead by manual 50 rotation of the valve 390 (Figs. 11 and 27) in the counter-clockwise direction, exactly the same as in the semi-automatic machine. The detent 445 in its movement in the cam-groove of the plate 720 (Fig. 28) will operate to stop the rotation of 55 the valve after chucking and again after the movement of the workhead has been begun, to insure, respectively, that the work is chucked properly before the workhead is moved into operating position and that the workhead is in operating position before the workhead is clamped. At the end of its rotation in the counter-clockwise direction, the detent 448 will enter the recess 721 in the cam-plate 720 under actuation of the spring 726, thereby locking the valve 390 against 65 clockwise movement until the detent is released.

In the fully automatic machine, the grinding-wheel is normally in dressing position when the machine is stopped and the various operating parts of the fluid-operated system are at this 75

time in the positions shown diagrammatically in Fig. 36.

To start the fully automatic machine, the operator presses the button 940 (Fig. 36). This closes a circuit from the main line L₁ through the automatic stop mechanism 710, the line 941, the line 942, the line 943, a terminal 944, switch 945, terminal 946, line 947, line 949, start button 948, line 948, line 950, line 951, solenoid 922 and line 952 to the main line L₂, the switch 945 being held closed at this time by the cam-projection 747 on the cam-bar 742 which is secured to the sleeve 740 (Figs. 31 and 36). This energizes the solenoid 922, causing the valve 920 to be moved vertically upwardly. The start-button 940 is a normally open button and will spring open as soon as it is released. However, the circuit to the solenoid 922 will be maintained by the contact-bar 926 which bridges the terminals 953 and 954 to connect the line 955 with the line 956 when the core-bar 921 is raised.

When the valve 920 is lifted the upper end of the piston 638 is put on supply from the pump line 935 through the ducts 655 and 663 and the underside of this piston is put on exhaust through the ducts 665, 661, 956, 957, and 958. Thus the piston 638 will be moved downwardly in the cylinder 639, causing the contact-bar 925 to break contact at the terminals 959 and 960 and alternately to make contact with the terminals 961 and 962. The downward movement of the piston 638 causes the grinding-wheel to be swung down from dressing into working position through operation of the rack 650, segment 652, gear 155 and segment 156 (Fig. 4).

It is to be noted that when the start-button 940 is pushed in, a circuit is made momentarily to the solenoid 878 from the main-line L₁ through the automatic stop mechanism 710, the line 941, the terminal 959, contact-bar 925, terminal 960, line 964, and solenoid 878 to the line 965 which is connected in any suitable manner (not shown) to the main line L₂. When this circuit is made the valve 875 is, of course, shifted to the right from the position shown in Fig. 36. This would ordinarily cause the piston 755 to be moved to the right also, but as the described circuit to the solenoid 878 is broken immediately after it is made, because of movement of the contact-bar 925 away from the terminals 959 and 960, nothing happens. The piston 755 does not move far enough to the right to cause any movement of the ratchet-member 762. The solenoid 878 itself is de-energized allowing the valve 875 to be returned to the left under actuation of the spring 879 and the piston 755 returns to the left.

When the contact-bar 925 makes contact with the terminals 961 and 962 at the lower end of the travel of the piston 638, the grinding wheel will have been swung down into operating position. This contact closes a circuit from the main line L₁ through the automatic stop 710, the line 941, the line 966, the terminal 961, the contact-bar 925, the terminal 962, the line 967, the solenoid 968 and the line 969 to the main line L₂. This energizes the solenoid 968, causing it to pull up the multiple-blade switch 978 and close the circuit to the main-drive motor 105, starting this motor and putting the machine into operation.

The rotating and swinging grinding-wheel will be fed into the gear to rough-grind the sides of a tooth-space, then the wheel will be withdrawn and the gear indexed, all as in the semi-automatic machine. The alternate feed and withdrawal movements of the wheel will continue until all

of the tooth-spaces of the gear have been ground. Then the automatic stop 710 will operate just as in the semi-automatic machine, to break the electrical circuit in which it is incorporated.

This will cause the solenoids 968 and 922 to be de-energized. De-energizing of the solenoid 968 will release the switch 970 and cause stoppage of the main-drive motor 105. De-energizing of the solenoid 922 will release the valve 920 and allow this valve to drop to its down position by gravity.

The return of the valve 920 to its down position will place the underside of the piston 638 on supply from the line 655 through the duct 665 and it will place the upper side of the piston 638 on exhaust from the line 663 through the line 659. This will cause the piston 638 to move upwardly in its cylinder, and the grinding wheel will be swung out of its working path into dressing position.

When the piston 638 has reached its uppermost position, the bar 925 will make contact with the terminals 959 and 960. The automatic stop mechanism 710 is of a type that resets itself automatically, as described in the Ford patent above mentioned. Hence, when the bar 925 makes contact with the terminals 959 and 960, a circuit will be closed from the line L₁ through the automatic stop mechanism, the line 941, the terminal 959, bar 925, terminal 960, line 964, and solenoid 878 to the main line 965. This will energize the solenoid 878 to cause it to shift the valve 875 to the right against the resistance of the spring 879.

The movement of the valve 875 to the right will cause the left side of the piston 755 to be placed on supply from the duct 955 through the duct 972, duct 973, duct 884, and duct 898. The right-hand side of the piston 755 will be placed on exhaust at the same time through the duct 896, duct 894, and duct 958 (Fig. 36). Thus, the piston 755 will be moved to the right, bringing the pawl 760 into engagement with the ratchet-member 762 and rotating this member. This will cause the pinion 207 to be rotated to raise the sleeve 740 and cause the roughing-cam 751 to be shifted out of engagement with the follower 45 and the finishing-cam 752 to be brought into engagement with this follower. It will also cause the cam-bar 742, which is secured to the sleeve 740, to be moved upwardly. In this movement, the roller 975 of the switch 945 will roll along the outer surface of the projection 747 of the cam-bar 742 and the rollers 976 and 977 of the switches 978 and 979, respectively, will roll up on the projections 746 and 749, respectively, of the cam-bar 742. The switch 945 will stay closed, therefore, and the switches 978 and 979 will be closed, see Fig. 34. Fig. 34 illustrates the positions of the several switches at an intermediate point in this movement of the cam-bar 742 and the cam-bar actually moves on in this movement, far enough beyond the point shown in Fig. 34 to cause the roller 975 of the switch 978 to drop off of the projection 746 again. Thus the switch 978 only makes momentary contact with the terminals 987 and 988.

When the switch 979 is closed, a circuit will be made from the line L₁ through the automatic stop 710, line 941, the line 942, the line 980, the terminal 981, the switch 979, the terminal 982, the line 983, and the solenoid 878 (Figs. 32 and 36) to the line 984 which is connected in any suitable manner (not shown) to the main line L₂. This will energize the solenoid 878 to cause the 75

- selector-valve 792 (Figs. 29 and 30) to be shifted upwardly from the position shown in Fig. 32. This will make the throttle-valve 857 (Fig. 33) effective to control the rate of movement of the 5 dressers across the grinding-wheel on the ensuing wheel-dressing operation so that the grinding-wheel may be dressed to a fine finish prior to finish-grinding, as determined by the adjustment of the valve 857.
- 10 The closing of the switch 978 will complete an electrical circuit from the main line L₁ through the automatic stop 710, the line 941, the line 942, the line 986, the terminal 987, the switch 978, the terminal 988, the line 989 and the solenoid 15 904 to the line 990 which is connected in any suitable manner (not shown) to the main-line L₂. This will energize the solenoid 904 and the valve 775 will be shifted to the right from the position shown in Fig. 36. The contact of the switch 978 20 with the terminals 987 and 988 is only momentary because the roller 976 rides up and over the prismatic projection 746 of the cam-bar 742 as the cam-bar is shifted by movement of the ratchet-member 762 as above described. The 25 circuit to the solenoid 904 is maintained, however, after it is completed, by the contact-bar 1012, which is carried by the core-bar 906 (Figs. 30 and 36).
- The circuit will then be from the main-line 30 L₁ through the automatic stop 710, line 941, line 942, terminal 1011, a normally closed switch 999, the function of which will hereinafter appear, terminal 1010, line 1009, terminal 1013, contact-bar 1012, terminal 1014 and line 1023, through 35 solenoid 904 to main-line 990.
- When the valve 775 is shifted to the right from the position shown in Fig. 36, the upper side (Fig. 32) of the piston 771 will be placed on supply (left-hand side in Fig. 36) and the lower 40 side (right-hand side in Fig. 36) of this piston on exhaust. Supply will be from the duct 955 through the duct 972, the duct 973, the duct 884 and the duct 776, while exhaust will be from the duct 771 through the duct 894 and the duct 45 958 back to the sump.
- The downward movement of the pistons 771 (rightward movement in Fig. 36) will release the T-bolts 770, thus unclamping the wheel-head 758 (Fig. 26) from the column 31.
- 50 As described above, one of the pistons 771 is connected to the lever 783 (Figs. 26, 32, and 36). In the downward movement of this particular piston, this lever will be moved to cause it to shift the valve 787 downwardly (to the right in Fig. 36) against the resistance of the spring 805. This places the upper side of the piston 790 (Fig. 29) (left-hand side in Fig. 36) on pressure and the lower side (right-hand side in Fig. 36) 55 on exhaust. Supply is from the duct 955 through the duct 972, duct 973, duct 992, duct 793 (Figs. 32 and 36) and duct 803, while exhaust is through the duct 801, duct 796, duct 868, and duct 958 back to the sump.
- 60 The downward movement of the piston 790 (rightward movement in Fig. 36) causes the pawl 813 to rotate the ratchet-wheel 814 (Figs. 26, 29, and 36) to advance the grinding-wheel toward the work. The stroke of the piston 790 is so adjusted by adjustment of the nut 835 (Fig. 70 29) that the grinding-wheel will be advanced a distance determined by the amount of stock to be removed in the dressing operation.
- Toward the end of the downward movement of the piston 790, the upper side of the recess 75 840 in the piston-rod 810 will strike the tail of
- the lever 837, rocking this lever about its pivot 838 and causing the valve 836 to be shifted upwardly (to the left in Fig. 36). This will put the left-hand side of the piston 506 (Figs. 22 and 36) on pressure and the right-hand side on exhaust. The pressure fluid will be supplied from the duct 955 through the duct 972, the duct 973, the duct 842, and the duct 520. Exhaust will be through the duct 524, the duct 846, (Figs. 29, 32, and 36) the duct 855, the selector valve 792, the 10 throttle-valve 857 (Fig. 33), the duct 868 (Fig. 36) and duct 958 back to the sump.
- With the left-hand end of the piston 506 on pressure, and the right-hand end on exhaust, the piston 506 will be moved to the right from 15 the position shown in Figs. 22 and 36 and thus the side and end dressers will be actuated to move in one direction across the grinding wheel and dress the same.
- There is a rod 995 (Fig. 36) secured to the piston 506 in the fully automatic machine. This rod is formed with a lower cam-surface 996 and with an upper cam-surface 997. The lower cam-surface 996 cooperates with a roller 998 that is carried by the pivoted switch-arm 999. 20
- 1000 designates a switch-member which is pivotally mounted at 1001 on the machine in proximity to the cam-bar 995. There is switch-arm 1002 pivotally mounted at 1003 on the switch 1000. This switch-arm 1002 is adapted to close a circuit through the terminals 1004 and 1005 and it is constantly urged upwardly toward contact with these terminals by a coil-spring 1006. 25
- There is a spring-pressed plunger 1007 mounted in the body of the switch 1000. This plunger is provided with a beveled end-surface 1008 that is adapted to ride on the inclined surface 997 of the cam-bar 995. 30
- As the piston 506 travels to the right, actuating the dressing mechanism, as above described, the roller 998 of the switch 999 rides off of the horizontal portion of the cam-surface 996 of the cam-bar 995 and up on the inclined portion of this cam-surface. This allows the switch 999 to 35 spring open, breaking the circuit to the solenoid 904. Thus the solenoid is de-energized and the valve 775 is allowed to return to the left to the position shown in Fig. 36 under actuation of the spring 905. This places the duct 771 leading to the right hand side of the piston 771 on supply from the ducts 884 and 973 while the duct 776 leading to the left-hand side of the piston 771 is placed on exhaust through the ducts 894 and 958. Thus, the T-bolts 770 are moved 40 back again into clamping position to clamp the wheel-head 758 to the column 31. 45
- As one of the pistons 771 moves to the left (upwardly in Fig. 32), the lever-arm 783 secured to this piston moves away from the stem of the valve 787 and this valve is returned to the left to the position shown in Fig. 36 (to its upper position in Fig. 32) by action of the spring 805. This places the duct 801 leading to the right-hand side of the piston 790 (lower side in Fig. 29) 50 on supply from the duct 992, and the duct 803 leading to the left-hand side of this piston (upper side in Fig. 29) on exhaust through the line 992. 55
- Thus the piston 790 is moved to the left in Fig. 36 (upwardly in Fig. 29). In this movement, the pawl 813 carried by the piston-rod 810 ratchets idly over the teeth of the ratchet-wheel 814, but the lower side-wall of the recess 840 in the piston-rod 810 (Fig. 29) strikes the tail of the lever 837. This causes the lever to be 60
- 65 65
- 70 70
- 75 75

rocked about its pivot to the position shown in Fig. 29, allowing the valve 836 to drop by gravity back to the position shown in Fig. 29.

This places the duct 524 leading to the right side of the piston 506 on supply from the duct 842, while the duct 520 leading to the left side of the piston 506 is placed on exhaust through the ducts 848 and 855, the selector-valve 792, throttle-valve 857 and the duct 868. Thus, the piston 506 is moved back to the left to the position shown in Figs. 22 and 36 and the dressing diamonds are passed back across the grinding-wheel, completing the finish-dressing operation at the rate determined by the setting of the throttle valve 857.

Now when the piston 506 was moved to the right as above described, the cam-surface 997 of the cam-bar 995 caused the plunger 1007 of the switch 1000 to move upwardly but the switch itself was not moved about its pivot 1001. The cam-bar simply passed under the plunger 1007 to reach the position indicated in dotted lines at 995' in Fig. 36. When the piston 506 moves back to the left, as just described, however, the end of the cam-bar 995 will engage the plunger 1007 and rock the switch 1000 about its pivot 1001 to cause the switch-arm 1002 to make contact with the terminals 1004 and 1005. This contact is only momentary and only continues until the end of the cam-bar 995 has ridden clear of the plunger 1007. Then the switch 1000 rocks back, breaking the circuit across the terminals 1004 and 1005 and the plunger 1007 drops back on to the cam surface 997 of the cam-bar. The momentary contact made by the switch-arm 1002 lasts long enough, however, to energize the solenoid 922, the circuit to this solenoid being made from the main line L₁ through the automatic stop 710, the lines 941, 942, 943, terminal 944, switch 945, terminal 946, line 947, terminal 1004, switch-arm 1002, terminal 1005, lines 950 and 951, solenoid 922 and line 952 to the main-line L₂.

When the piston 506 moves back to the left, the roller 998 of the switch 999 rides back on to the horizontal portion of the cam-surface 996 of the cam-bar 995. Thus the switch 999 is closed again to make contact with the terminals 1010 and 1011. Nothing happens, however, with the closing of this switch because the circuit to this switch remains open since the contact-bar 1012 carried by the core-bar 986 of the solenoid 984 is at this time out of contact with its terminals 1013 and 1014.

The energizing of the solenoid 922 has, however, the effect of shifting the valve 920 upwardly. This causes the piston 638 to be moved downwardly, swinging the dressed grinding-wheel down again into operative position.

As the piston 638 moves downwardly, it moves the contact-bar 925 away from the terminals 959 and 960 breaking the circuit to the solenoid 878. This allows the valve 875 to return to the left to the position shown in Fig. 36 under actuation of the spring 879 (to its upper position as shown in Fig. 30). This puts the right-hand end of the piston 755 on pressure (under side in Fig. 31) and the left-hand end of this piston (upper side in Fig. 31) on exhaust and so the piston 755 is moved back to the left as shown in Fig. 36. This simply causes the pawl 760 to ratchet back idly over the ratchet-member 762 and return to initial position.

When the piston 638 reaches its lowermost position, the bar 925 carried by this piston will make

contact with the terminals 961 and 962, closing the circuit to the main drive motor 105 again. The machine will then go through its cycle of operation again. The swinging and rotating grinding-wheel will be fed into a tooth space to finish grind the tooth space. Then the wheel will be withdrawn and the gear indexed and the alternate feeding and withdrawing for indexing will proceed until all of the tooth spaces of the gear have been finish-ground. During this phase of the operation, the feed and withdrawal motions of the grinding-wheel will be controlled, of course, by the finishing-cam track 752 of the cam 750 so that the grinding-wheel will be fed into each gear tooth-space at a slower rate than during rough grinding and the wheel will be allowed to dwell momentarily in each tooth space, after it has reached full depth position, in order to insure the highest degree of accuracy in the finished gear.

After all of the tooth spaces of the gear have been finish-ground, the automatic stop mechanism 710 will again function automatically to break the circuit to the main drive motor 105 and to the solenoid 922. This will stop the main drive motor and will allow the valve 920 to drop down to its lower position by gravity. While the electrical circuit through the automatic stop mechanism is broken automatically in the functioning of this mechanism, it is understood that the circuit through the stop itself is re-made instantly after its breakage, this being the method of operation of the type of stop mechanisms such as would be employed on this machine.

The movement of the valve 920 to its lower position puts the lower side of the piston 638 on supply and the upper side on exhaust. This piston is again moved upwardly. This causes the grinding wheel to be again swung upwardly, out of its working path into dressing position.

At the end of its upward movement, the piston 638 causes the contact bar 925 to make contact with the terminals 959 and 960. This closes the circuit to the solenoid 878. This energizes the solenoid 878 and causes the valve 875 to be shifted to the right from the position shown in Fig. 36. This puts the left-hand side of the piston 755 on supply and the right-hand side on exhaust and this piston is therefore moved again to the right from the position shown in Fig. 36. The pawl 760 carried by the piston-rod 759 therefore again engages the ratchet member 762, rotating this member. This rotates the pinion 207 again shifting the sleeve 740 and cam-bar 742 upwardly. The face of the finishing-cam track 752 of the cam 750 is wide enough to remain in engagement with the follower 45 throughout this last-named movement.

In this second upward movement of the cam-bar 742, the roller 911 of the switch 979 rides off of the projection 749 of the cam-bar; the roller 975 of the switch 945 rolls off of the projection 741 of the cam-bar; the roller 976 of the switch 978 rolls up on to the projection 747 of the cam-bar; and the roller 1016 of the switch 1017 rolls up on to the projection 745 of the cam-bar, see Fig. 35.

When the roller 911 of the switch 979 rolls off of the projection 749 of the cam-bar, the switch 979 springs open to break the circuit to the solenoid 870. This de-energizes this solenoid and allows the selector valve 792 to be shifted back to the position shown in Fig. 36 under actuation of the spring 805. This places the throttle-valve 858 (Figs. 33 and 36) again in control of the rate of exhaust from the dresser-control valve 836. The

throttle valve 858 is adjusted to produce a finish on the grinding wheel suitable for a rough-grinding operation, and hence, such a finish will be produced on the wheel in the ensuing dressing 5 operation.

When the roller 975 of the switch 945 drops off the projection 747 of the cam-bar 742, the switch 945 springs open, opening the starting circuit to the machine.

When the switch 1017 is closed a circuit is completed from the line L₁ through the automatic stop 710, the lines 942 and 1018, the terminal 1019, the switch 1017, the terminal 1020, the line 1021, the line 1022 and the solenoid 730 to the line 1024 which is connected in any suitable manner (not shown) to the main line L₂. This energizes the solenoid 730 (Figs. 27 and 36), causing the core-bar 731 to swing the lever-arm 733 about its pivot 724. This forces the shaft 722 to the left from the position shown in Figs. 27 and 36 against the resistance of the spring 726 and the detent 445 is disengaged from the recess 721. The coil-spring 727 comes into action immediately, then, and rotates the valve 390 in a clockwise direction. This causes the right-hand side of the piston 262 to be placed on supply and the left-hand side on exhaust to cause the workhead to be unclamped from the base 235. It also causes the left-hand end of the piston 240 to be placed on supply and the right-hand end on exhaust, whereby the workhead is withdrawn to loading position. Finally it causes the right hand end of the piston 380 to be placed on supply to force the draw-bar 365 forward in the work spindle against the resistance of the coil-spring 366, thus dechucking the work. Thus the workhead is unclamped, withdrawn to loading position and the completed gear automatically dechucked.

When the roller 976 of the switch 978 rides up on the projection 747 of the cam-bar 742, the switch 978 is closed to complete a circuit to the solenoid 904 from the main line L₁ through the automatic stop 710, the lines 941, 942, and 986, the terminal 987, the switch 978, the terminal 958, the line 989, the solenoid 904 and line 990. This energizes the solenoid 904 to shift the valve 775 to the right from the position shown in Fig. 36. This causes the pistons 771 to be also moved to the right, releasing the T-bolts 770 and unclamping the wheel-head 758 from the column 31 of the machine. One of the pistons 771 (Figs. 32 and 36) in its movement rocks the lever 783 about its pivot 784, causing the valve 787 to be shifted to the right from the position shown in Fig. 36.

This causes the piston 799 to be again moved to the right from the position shown in Fig. 36, causing the pawl 813 to again impart rotational movement to the ratchet wheel 814 (Figs. 26, 29, and 36), thus advancing the wheel-head 758 and with it the grinding wheel toward the work.

In its movement, the piston-rod 810 swings the lever 837 about its pivot 838, causing the valve 833 to be shifted to the left from the position shown in Fig. 36. This puts the left-hand end of the piston 506 on supply and the right-hand end on exhaust. Thus, the dressing mechanism is again actuated to dress the grinding wheel. In this dressing operation, as stated above, the throttle valve 858 controls the rate of movement of the dressing diamonds across the grinding wheel and so the wheel is dressed in a manner suitable for a succeeding rough-grinding operation.

When the piston 536 moves to the right, the cam-bar 995 again rides clear of the plunger 1007

of the switch 1000. This plunger again drops down behind the end of the cam-bar. The roller 998 also rides up on the inclined surface 996 of the cam-bar 995, breaking the circuit to the solenoid 904 through the contact-bar 1012.

This de-energizes the solenoid 904, allowing the valve 775 to be returned to the left to the position shown in Fig. 36 under actuation of the spring 805. This again causes the piston 771 to be moved to the left to the position shown in Fig. 36 to again cause the wheel-head 758 to be clamped to the column 31.

In this movement, the piston 771 which is connected to the lever 733, moves this lever upwardly (to the left in Fig. 36) allowing the valve 787 to be returned to the position shown in Fig. 36 under actuation of the spring 805. This causes the piston 790 to be moved to the left, returning the pawl 813 to initial position. In this return movement of the piston 790, the lever 837 will be rocked back to the position shown in Fig. 36, allowing the valve 833 to return to the position shown in this figure. This will place the right-hand side of the piston 506 on supply and the left-hand side on exhaust and the piston 506 will be returned to the position in Fig. 36 causing the dressing diamonds to make their return passage over the grinding-wheel.

In this return movement of the piston 506, the roller 998 will again ride on to the horizontal portion of the cam surface 996 of the cam-bar 995 and the switch 999 will again be closed. Nothing will happen, however, because at this time the contact bar 1012 is away from the terminals 1013 and 1014. In the return movement of the piston 506, the switch 1000 will again be rocked about its pivot 1001 to cause the switch-arm 1002 to make contact with the terminals 1004 and 1005.

Normally, the closing of the switch 1000 would restart the machine, by closing the circuit to the solenoid 922 which would in turn cause the piston 638 to move downwardly bringing the contact-bar 925 into engagement with the terminals 961 and 962 to close the circuit to the main-drive motor of the machine. This time, however, the closing of the switch 1000 will not close the circuit to the solenoid 922 because the switch 945 which is included in this circuit is at this time open, the roller 975 of this switch having dropped off the projection 747 of the cam-bar 742 in the last described upward movement of this cam bar. Accordingly, the machine will be entirely stopped.

To re-start the machine, the operator must return the sleeve 140 to its lowermost position by manual rotation of the shaft 206. This movement causes the roller 975 to ride up on the projection 748 and close the starting circuit of the machine, and it also resets all of the other switches 1017, 978 and 979 as well as the ratchet-member 762. To start the machine again, the operator presses the stop-button 940.

In the operation of the machine, then, the grinding-wheel is first swung down from dressing to working position by energizing the solenoid 922 to move the piston 638 downwardly. At the end of the downward movement of this piston 638, the main drive motor is started, starting the swinging and feed movements of the grinding wheel and putting the machine into operation. The machine goes through its cycle of operations, the wheel being fed into a tooth-space of the gear to grind the same and being then withdrawn and the gear being indexed. During this first cycle of operation, the track 75

751 of the cam 750 controls the feeding movements of the grinding wheel so that the gear is rough-ground.

When all of the tooth-spaces of the gear have been ground, the automatic stop 710 functions to break the circuit to the solenoid 922, causing the piston 638 to be moved upwardly to break the circuit to the main drive motor and stop the swinging and feed movements of the grinding 10 wheel. The upward movement of the piston 638 also swings the grinding wheel up into dressing position and when the grinding wheel has reached dressing position, the bar 925 makes contact with the terminals 959 and 960 to cause the 15 sleeve 740 to be moved upwardly. This shifts the roughing-cam 751 out of engagement with the follower 45 and moves the finishing-cam 750 into engagement with the follower. It also closes the switch 978 and the switch 979. The latter 20 switch causes the selector-valve 792 to be shifted so that in the next dressing operation the wheel will be dressed for finish-grinding. The closing of the switch 978 causes the wheel-head to be unclamped from the column 31 and the wheel 25 to be advanced into the dressing diamonds.

Then the wheel is dressed. At the end of the return movement of the dressing diamonds, the solenoid 922 is again energized, the wheel is swung down again into working position and the 30 main-drive motor is again started.

The machine again goes through a cycle of operation, the rotating and swinging grinding-wheel being again fed successively into each tooth space of the gear to finish-grind the same. At 35 the end of the finish grinding operation, when all of the tooth spaces of the gear have been finish ground, the automatic stop 710 is again tripped to de-energize the solenoid 922 and cause the piston 638 to be again moved upwardly, 40 breaking the circuit to the main drive motor 105 and stopping the swinging and feed motions of the machine. In the upward movement of the piston 638, the grinding wheel is again swung up to dressing position. When the grinding wheel 45 is in this position, the bar 925 again makes contact with the terminals 959 and 960 to again cause the sleeve 740 to be shifted upwardly. This time, the switch 1017 is closed, energizing the solenoid 730 to cause the valve 390 to be 50 released and allowing this valve to be rotated by the spring 727. This causes the work-head to be unclamped, withdrawn to loading position and the work to be dechucked.

In this last described upward movement of the 55 sleeve 740, also, the switch 978 is again closed but the switch 979 is opened. The opening of the latter de-energizes the solenoid 878 which controls the movement of the selector valve 792 and this valve is shifted by the spring 885 so that the 60 next dressing operation will dress the wheel in a manner suitable for rough-grinding. The closing of the switch 978 causes the wheel-head to be unclamped from the column 31, advanced toward the dressing mechanism and the dressing 65 mechanism to be actuated. In the return stroke of the dressers, the switch 1000 is closed, but since the starting circuit of the machine is now open, the machine does not re-start. To grind another gear, the operator must first return the sleeve 740 to initial position and push in the 70 start-button 940.

While the invention has been described in connection with a machine for grinding spiral bevel and hypoid gears with a swinging grinding 75 wheel, it will be understood that various features

of the invention are applicable to the grinding of such gears with other types of grinding-wheels and that, moreover, the features of the invention are applicable to the grinding of various other types of gears. Certain features of the 5 invention, in fact, are applicable to other types of machines than gear grinding machines. In general, it may be said that while the invention has been described in connection with particular embodiments thereof, it will be understood that 10 it is capable of further modification and use and this application is intended to cover any variations, uses or adaptations of the invention, following, in general, the principles of the invention and including such departures from the present 15 disclosure as come within known or customary practice in the art to which the invention pertains and as may be applied to the essential features hereinbefore set forth and as fall within the scope of the invention or the limits of the 20 appended claims.

Having thus described our invention, what we claim is:

1. In a machine for grinding gears, a tool support, a grinding-wheel journaled therein, a work support, separate cams for producing relative feed movements between the wheel and work support during rough-grinding and during finish-grinding, respectively, and means for bringing said cams selectively into operative position. 25

2. In a machine for grinding longitudinally curved tooth gears, a head provided with spaced bearings, a quill mounted in said bearings for longitudinal reciprocating movement therein, a grinding wheel journaled in said quill, a work support, means for producing alternate relative movements of feed and withdrawal between the grinding wheel and the work support comprising a rotary cam and a follower, one of which is secured to the quill and the other of which is mounted on said head, means for rotating said cam and means for indexing the work during the periods of withdrawal. 35

3. In a machine for grinding gears, a head provided with spaced bearings, a quill mounted in said bearings for endwise reciprocating movement, a tool spindle journaled in said quill and held against endwise movement relative thereto, a grinding-wheel secured to said spindle, a work support, a cam-follower secured to said quill at a point intermediate said bearings, a rotary shaft journaled in said head with its axis extending at right angles to the direction of movement of said quill, a cam secured to said shaft and engaging said follower, and means for rotating said shaft to impart reciprocating movements to said quill. 50

4. In a machine for grinding longitudinally curved tooth gears, a work support, a rotatable tool support, a grinding-wheel journaled in the tool support, means for rotating the grinding wheel on its axis, means for simultaneously oscillating the tool support through a limited working path to cause the wheel to grind tooth surfaces of the gear for their full length, means for adjusting the tool support to determine the position of the working path of the wheel about the axis of swing of said tool support, fluid-pressure operated means for swinging said tool support beyond its working path to move the wheel to dressing position, and a stop on the frame for limiting said last-named movement whereby to stop the grinding-wheel always in the same position for dressing regardless of the extent of its working path and the position of that path. 65

5. In a machine for producing gears, tool 70

- mechanism, a work support, a work spindle journaled in said work support, fluid-pressure operated means for moving the work support to and from operative position, fluid-pressure operated 5 means for clamping the work support in operative position, fluid-pressure operated means for chucking a work-piece on said work support, and a single control-valve for controlling the operation of said three fluid-pressure operated means.
- 10 6. In a machine for producing gears, tool mechanism, a work support, a work spindle journaled in the work support, means for moving the work support to and from operative position, means for clamping the work support in operative 15 position, means for chucking a work-piece on the work support, and control means for said aforementioned means whereby chucking of the work-piece must be effected before the work support can be moved into operating position and 20 whereby the work support must be in operating position before it can be clamped.
7. In a grinding machine, a grinding-member, a dressing tool, means for moving the tool across the surface of the grinding-member to dress the 25 same, and separate means selectively operable to predetermine the rate of movement of the dressing tool across said member.
8. In a grinding machine, a grinding-member, a work support, means for actuating said grinding-member to effect successively rough and 30 finish-grinding operations on the work, a dressing tool, means for moving said tool across the surface of the grinding member to dress the same, separate means selectively operable to control the 35 rate of movement of said dressing tool, said means being adjustable so that the rate of movement of the tool is faster in dressing said member prior to a rough-grinding operation than in dressing it prior to a finish-grinding operation, 40 and means operative automatically, between the rough and finish-grinding operations and vice versa to preselect the rate control means which is to be operative during a dressing operation.
9. In a machine for grinding gears, a work support, a grinding-member, a dressing tool, means for producing relative movements between the grinding-member and the work support to grind the work, separate members for controlling said movements to effect rough-grinding and finish- 45 50 grinding operations, respectively, and means for automatically actuating the dressing tool to dress the grinding-member between the rough and finish-grinding operations.
10. In a machine for grinding gears, a work support, a grinding-member, a dressing tool, means for producing relative movements between the grinding-member and the work support to grind the work, separate members for controlling said means to effect rough-grinding and finish- 55 60 grinding operations, respectively, and means for automatically actuating the dressing tool to dress the grinding-member and for advancing the grinding-member toward the work to compensate for wear of said member between the rough and finish-grinding operations.
11. In a machine for grinding gears, a frame, a work support mounted on the frame, dressing mechanism mounted on the frame, a movable tool support mounted on the frame, a grinding- 65 member mounted on the tool support, means for actuating said member to effect rough and finish-grinding operations on the work, means for automatically moving the tool support to move the grinding-member from operating position to dressing position and back again between rough 70 75
- and finish-grinding operations, and means for automatically dressing the grinding-member while in dressing position.
12. In a machine for grinding gears, a frame, dressing mechanism mounted on the frame, a quill journaled in the frame, a grinding-wheel journaled in the quill, means for rotating the grinding wheel, means for swinging the quill on its axis including a set of differential gears, means for holding one element of the differential 10 stationary and for actuating the other element of the differential to swing the quill through a limited angle to effect movement of the grinding-wheel in its working path and means for actuating the first-named element of the differential to move the grinding-wheel out of its working path to dressing position. 15
13. In a machine for grinding longitudinally curved tooth gears, a frame, dressing mechanism mounted on the frame, a cupped grinding-wheel, means for rotating the grinding wheel, means for simultaneously swinging the grinding-wheel in a limited working path to pass the grinding wheel longitudinally over the tooth surfaces of the gear to be ground, and means for swinging said grinding-wheel about the axis on which it swings during grinding but beyond its working path to move the wheel to dressing position. 20 25
14. In a machine for grinding gears, a frame, dressing mechanism mounted on the frame, a cupped grinding-wheel, means for rotating the grinding-wheel, means for simultaneously swinging the grinding-wheel in a limited working path, 30 and means for periodically swinging said grinding-wheel beyond said working path to move the wheel to dressing position. 35
15. In a machine for grinding gears, a frame, dressing mechanism mounted on the frame, a reciprocable support, a grinding-wheel journaled in said support, means for rotating the grinding-wheel, means for actuating said support to move the grinding-wheel from dressing to operating position, separate means for reciprocating said support to cause said wheel, when in operating 40 45 position, to grind tooth surfaces of a gear for their full length, and means whereby movement of the grinding-wheel to operating position renders the last-named means operative.
16. In a machine for grinding longitudinally curved tooth gears, a frame, a quill reciprocably and rotatably mounted on the frame, a grinding wheel spindle journaled in the quill with its axis inclined to the axis of the quill, a cupped grinding wheel secured to the wheel spindle, means for rotating said wheel comprising a shaft that is journaled coaxially in the quill, a shaft which is journaled in the quill parallel to the wheel spindle, a pair of angular bevel gears connecting said shafts, and a belt and pulley drive connecting the second shaft and the wheel spindle, means for oscillating the quill to swing the wheel longitudinally along the tooth surfaces of the gear, and means for reciprocating the quill axially. 50 55 60
17. In a machine for producing gears, a head provided with spaced bearings, a quill mounted in said bearings for oscillating and endwise reciprocating movements, a tool spindle journaled in said quill, a tool secured to said spindle, a work support, a follower secured to said quill at a point intermediate said bearings, a rotary shaft journaled in said head with its axis extended at right angles to the direction of reciprocating movement of said quill, a cam secured to said shaft and engaging said follower, means for rotating 65 70 75

- said spindle, means for oscillating said quill, and means for rotating said shaft to impart reciprocating movements to said quill.
18. In a machine for grinding gears, a tool support, a grinding-wheel journaled therein, a work support, a rotary shaft, separate cams secured to said shaft and adapted, respectively, to produce alternate movements of feed and withdrawal between said supports during rough-grinding and finish-grinding, respectively, a follower secured to one of said supports and adapted to be engaged selectively with either of said cams, means for shifting said shaft axially to bring either cam into operative engagement with the follower, and means for rotating said shaft.
19. In a machine for grinding gears, a work support, a tool support, a grinding-wheel rotatably mounted on the tool support, means for effecting the operating cycle of the machine comprising relative feed of the grinding wheel into the work, relative withdrawal of the grinding wheel, and indexing of the work, means for automatically stopping the operating cycle of the machine when a gear has been rough-ground and for automatically moving the grinding-wheel to dressing position, means for automatically dressing the wheel when it reaches dressing position, means for automatically returning the wheel to operative position after it has been dressed, and means for automatically restarting the operating cycle of the machine when the wheel is returned to operating position.
20. In a machine for grinding longitudinally curved tooth gears, a frame, a head slidably mounted on the frame, a quill reciprocably and oscillatably mounted in the head, a cupped grinding-wheel journaled in the quill, means for reciprocating and for oscillating said quill, means for adjusting the head on the frame in a direction axial of the quill, means for securing the head in any adjusted position after adjustment comprising a plurality of T-bolts engageable in T-slots in the frame, fluid-pressure operated means for controlling the position of each bolt and a single valve for controlling all of said fluid-pressure operated means.
21. In a machine for producing gears, a work support, a work spindle journaled in the work support, fluid-pressure operated means for moving the work support to and from operative position, fluid-pressure operated means for clamping the work-support in operative position, a single control valve for said two fluid-pressure operated means operable in one direction to cause said two fluid-pressure operated means to function successively, means for stopping the control valve when it has moved far enough to actuate the first-named fluid-pressure operated means, and means for releasing said valve to permit its continued movement so as to enable operation of said second fluid-pressure operated means.
22. In a machine for grinding gears, a frame, a support movably mounted on the frame, a dressing mechanism mounted on the frame, a grinding-wheel journaled in said support, means for reciprocating the support in a limited working path to effect grinding of the tooth surfaces, fluid-pressure operated mechanism for moving said support on the frame in the direction of its working path but beyond the same to move the grinding-wheel from operating to dressing position, means for adjusting said support relative to said fluid-pressure operated mechanism in the direction of movement of said support to determine the position of its working path, and

cooperating stops on the frame and support for limiting the movement of the support when the wheel is moved to dressing position so that the wheel is always moved to the same position for dressing.

23. In a machine for grinding gears, a frame, dressing mechanism mounted on the frame, a quill journaled in the frame, a grinding-wheel journaled in said quill, means for rotating the grinding-wheel, means for swinging said quill on its axis including a set of differential gears, means for holding one element of the differential stationary, means for actuating another element of the differential to swing the quill through a limited angle to effect movement of the grinding-wheel in its working path, fluid-pressure operated means including a cylinder and a piston reciprocable therein for actuating the first-named element of the differential, when released, to swing the quill through an extended angle to move the grinding wheel out of its working path to dressing position, means for adjusting the first-named element of this differential independently of said fluid-pressure operated means to adjust the path of swing of the quill, and cooperating stops on the frame and quill for limiting movement of the quill under actuation of said fluid-pressure operated means so that the wheel is always moved to the same position for dressing.

24. In a machine for producing gears, a work support, a work spindle journaled in the work support, fluid-pressure operated means for moving the work support to and from operative position, fluid-pressure operated means for clamping the work support in operative position, fluid-pressure operated chucking mechanism for the work spindle, a single control valve for said three fluid-pressure operated means, said valve being movable in one direction to cause, successively, chucking of the work, movement of the work support into operating position and clamping of the work support in operating position, means operable to cause a dwell in the movement of the control valve between the chucking and work support moving positions to insure chucking of the work before movement of the work support, and means operable to cause a dwell in the movement of the control valve between the work support moving position and the work support clamping position to insure that the work support is in operating position before it is clamped.

25. In a machine for producing gears, a work support, a work spindle journaled in the work support, means for moving the work support to and from operating position, means for clamping the work support in operating position, means for chucking a work-piece on the work spindle and means for automatically releasing the work support, moving the same to inoperative position and releasing the chucking mechanism when the operations of the machine are finished.

26. In a machine for producing gears, a work support, a work spindle journaled in the work support, fluid-pressure operated means for moving the work support to and from operating position, fluid-pressure operated means for clamping the work support in operating position, fluid-pressure operated means for chucking a work-piece on the work spindle, and a single control valve operable in one direction to effect release of the work-head, movement of the same to inoperative position, and dechucking of the work.

27. In a machine for grinding gears, a work support, a frame, a tool support movable on the

frame, a grinding-wheel journaled in the tool support, means for rotating the grinding-wheel, dressing mechanism, means for clamping the tool support in operative position, means for automatically dressing the grinding-wheel, and means for automatically releasing the tool support, advancing the same to compensate for wear of the wheel, and then reclamping the same to the frame, each time the wheel is dressed.

28. In a machine for grinding longitudinally curved tooth gears, a work support, a tool support provided with spaced bearings, a quill rotatably and reciprocably mounted in said spaced bearings, a grinding wheel spindle journaled in said quill with its axis inclined to the axis of the quill, a cupped grinding wheel secured to the wheel spindle, means for rotating the grinding wheel, a cam and a cam-follower one of which is secured to the quill at a point between said bearings and the other which is secured to the tool support, means for oscillating the quill to swing the grinding wheel longitudinally along the tooth surfaces of the gear, means for actuating the cam to produce alternate movements of feed and withdrawal between the grinding wheel and the work, and means for indexing the work during the periods of withdrawal.

29. In a machine for grinding gears, a work support, a reciprocable tool support, a dressing mechanism, a grinding wheel journaled in the tool support, means for rotating the grinding wheel on its axis, means for reciprocating the tool support including a set of differential gears, means for holding one element of the differential against movement during grinding and for actuating the other elements of the differential to impart a reciprocating movement to the tool support in a limited working path, and means for releasing and actuating the first named element of the differential to impart an extended stroke to the tool support to move the grinding wheel to dressing position.

30. In a machine for grinding gears, a work support, a reciprocable tool support, a dressing mechanism, a grinding wheel journaled in the tool support, means for rotating the grinding wheel on its axis, means for reciprocating the tool support including a set of differential gears, means for holding one element of the differential against movement during grinding and for actuating the other elements of the differential to impart a reciprocating movement to the tool support in a limited working path, and means for releasing and automatically actuating the first named element, after predetermined operations on the blank have been completed, to impart an extended stroke to the tool support to move the grinding wheel to dressing position.

31. In a machine for grinding longitudinally curved tooth gears, a cupped grinding wheel, means for rotating the grinding wheel, means for simultaneously swinging the grinding wheel in a limited working path to effect the grinding operation, means for swinging said grinding wheel beyond said working path to move the wheel to dressing position, dressing mechanism positioned in line with the path of extended movement of the wheel, and means for actuating the dressing mechanism when the wheel reaches dressing position to dress the wheel.

32. In a machine for grinding longitudinally curved tooth gears, a cupped grinding wheel, means for rotating the grinding wheel, means for simultaneously swinging the grinding wheel in a limited work path to effect the grinding operation, means for swinging the wheel beyond said working path to move the wheel to dressing position, dressing mechanism positioned in line with the path of extended movement of the wheel, and means for automatically advancing the grinding wheel in the direction of its axis of swing and for actuating said dressing mechanism when the wheel reaches dressing position.

33. In a machine for grinding longitudinally curved tooth gears, a cupped grinding wheel, having opposite side surfaces inclined to one another, means for rotating the grinding wheel, means for simultaneously swinging the grinding wheel in a limited work path to effect the grinding operation, dressing mechanism comprising a pair of dressers for dressing, respectively, opposite sides of the wheel, said dressers being mounted to move in paths inclined to one another at an angle equal to the angle between opposite sides of the wheel, and means operable after a predetermined number of grinding operations to move the wheel beyond its working path to position the wheel between the paths of movement of the dressers, and means for actuating said dressers to dress said wheel.

34. In a machine for grinding gears, a frame, a work support mounted on the frame, a tool support adjustable on the frame, dressing mechanism mounted on the frame, a tool carrier reciprocable on the tool support, a grinding wheel journaled in the carrier, means for adjusting the tool support into operative relation with the work support and for clamping the same in operative position, means for rotating the grinding wheel, means for imparting a reciprocating movement to the tool carrier in a limited working path, means for moving the tool carrier beyond its working path to move the grinding wheel to dressing position, and means operative on said movement for automatically unclamping the tool support and moving the same to advance the grinding wheel into the dressing mechanism.

35. In a machine for grinding gears, a frame, a work support mounted on the frame, a tool support adjustable on the frame, dressing mechanism mounted on the frame, a tool carrier reciprocable on the tool support, a grinding wheel journaled in the carrier, means for adjusting the tool support into operative relation with the work support and for clamping the same in operative position, means for rotating the grinding wheel, means for imparting reciprocating movement to the tool carrier in a limited working path, means for moving the tool carrier beyond its working path to move the grinding wheel to dressing position, means operative on said movement for automatically unclamping the tool support and moving the same to advance the grinding wheel into dressing position, and means for thereafter automatically actuating the dressing mechanism.
